CENTRALIZED TRAFFIC CONTROLLING
SYSTEM FOR RAILROADS

Thomas J. Judge, Rochester, N. Y., assignor to
General Railway Signal Company, Rochester,
N. Y.

Application September 27, 1932, Serial No. 635,062

40 Claims. (Cl. 177—353)

This invention relates to centralized traffic controlling systems for railroads and more particularly to a system whereby railroad traffic is controlled from a control office and the location of trains as well as the condition of traffic controlling devices at remote locations are indicated to an attendant at the control office. Such a system is supplemented by the well-known automatic block signals and other local means which are ordinarily provided to prevent unsafe train movements, improper operation of track switches or the like. The system of this invention comprises a communication system extending from the control office to field stations located at appropriate points in the territory under the supervision of an attendant or operator.

Such a communication system is of particular utility in enabling the operator to select and actuate a relay or control device for each switch or signal at any desired station in his territory to effect the actuation of the switches and signals to different positions at his will, subject to their automatic control which is ordinarily provided to prevent unsafe conditioning. This selection and actuation feature is conveniently referred to as transmission of controls and may be effected by a manual operation under the control of the operator. The communication system may also be used to transmit to the operator indications of the positions of switches and signals, the presence or absence of trains and such other indications as may be useful in directing and supervising train movements in various track sections. Such a function is conveniently termed transmission of indications and may be automatically effected when a new indication is to be transmitted to the control office either when the system is at rest or when it is being used to transmit controls from the control office.

The system of this disclosure is of the duplex coded type since the transmission of controls and the transmission of indications can occur simultaneously and since the transmission of controls and indications is by means of code impulses. This feature is so incorporated in the system that duplex or two-way transmission can simultaneously occur to and from the same station or to and from different stations.

This application is a continuation in part of my copending abandoned application Ser. No. 589,783 filed January 30, 1932.

The present invention may be considered as an improvement over the system disclosed in the prior application of N. D. Preston et al., Ser. No.

455,304, filed May 24, 1930, now Patent No. 2,129,183, dated Sept. 6, 1938. This prior application discloses a communication system of the duplex coded type providing the above-mentioned features over two circuits extending from the control office to the field stations. The invention of the present application is directed to the transmission of controls and indications by means of a single circuit extending from the control office to the field stations. By effecting such selection and transmission over a two-wire circuit obvious economies in the construction and maintenance of the line are realized.

Other objects and advantages of the present invention will be hereinafter set forth in the specification and claims and shown in the drawings. The present disclosure is intended to show only the elemental principles of the invention and in order to simplify the drawings and descriptive matter as much as possible only such portions of a complete system are illustrated as will most clearly convey the features disclosed.

In describing the invention in detail reference will be made to the accompanying drawings which illustrate in a diagrammatic manner the apparatus and circuits as employed in accordance with the present invention. Fig. 1 illustrates the apparatus and circuits employed at the control office. Fig. 2 illustrates the apparatus and circuits employed at one of the field stations. Fig. 3 illustrates a modification showing how two or more groups may be operated at the same station by using most of the equipment in common for all groups at the same station. The two wire line circuit connecting the control office with the field stations is shown in the upper portion of Figs. 1 and 2 and the operation of the apparatus at the control office and at the field station may be conveniently followed by placing the drawing of Fig. 2 to the right of Fig. 1.

Within the dotted rectangle in the upper central portion of Fig. 2, the extension of the two wire line circuit through other stations is indicated. It will be understood that the line circuit may extend through one or more additional field stations having apparatus and circuit arrangements practically the same as that shown in Fig. 2. As will be clearly pointed out in the following description, the points of difference in the circuit connections at different field stations are the distinctive connections of the code jumpers so that a particular field station will be fully responsive only to a particular code assigned to this field station.

GENERAL DESCRIPTION

No attempt has been made to show all of the apparatus, such as the total number of manual controls at the control office or the exact arrangement of the equipment at the field stations, since this arrangement may vary to suit local conditions. There may be included at the control office a number of groups of manually operable devices, each group corresponding to a field station and 10 being provided with an associated starting button. The operation of any one of these buttons puts the system through an operating cycle during which a station corresponding to the operated button will be selected.

15 These manually operable devices consist of switch machine levers, signal levers and the like for the purpose of controlling the various traffic devices at the selected field station. Only one lever is shown in the drawings of this application 20 since a complete description of the operation of such levers and the signals they control is given in the above-mentioned application Ser. No. 455,304. This above-mentioned application also discloses how a plurality of controls may be stored 25 by the operator and how these controls may be applied to the system in proper rotation when several starting buttons are actuated simultaneously or in rapid succession.

The controls are transmitted from the control 30 office over two line wires in series by means of a succession of positive and negative impulses arranged in code combinations, each particular combination of impulses being effective to select a corresponding field station. Following station 35 selection, additional code impulses are applied to the line for positioning the switch machine relay and the signal relays for the purpose of governing the traffic in the section of track associated with the selected station. The complete 40 circuit arrangement for actuating the switch machine and signals is not shown since it is now well known how these various devices operate when their circuits are properly governed by the relays operated from the control office.

45 If, while transmission of controls is taking place, no indications are being transmitted, the open periods of the line circuit are of substantially equal duration and the impulses for selecting the desired station and transmitting the 50 desired controls to the station follow each other in rapid succession.

The line relay in the control office and the line relay at the field stations are normally energized by current flowing in the line circuit from 55 a battery in the control office. When controls or indications are to be transmitted, the line circuit is opened momentarily to initiate the operation of the system after which the stepping relays at the control office go through an operating 60 cycle. The impulses which are connected to the line on subsequent closures are each effective to operate a stepping relay at both the control office and at the field station, irrespective of the polarity of the impulses. The stepping 65 relays at the station which will be selected go through the operating cycle in synchronism with those at the control office. The stepping relays at other stations operate during a portion 70 of the operating cycle only, since they are dropped out at different points during the cycle as the code directs. For the transmission of controls the polarity of each impulse is effective to build up a code combination for selecting the 75 desired station while the polarity of each im-

pulse transmitted after the station is selected determines the controls established thereat.

Indications are transmitted from the field stations over the same line circuit by causing the deenergized or open periods between successive 5 impulses to be either short or long. Combinations of short and long open periods between impulses are used to determine the selection of the station during transmission of indications as well as determining the indication which will 10 be displayed after the station is selected. In accordance with the present invention, these combinations of short and long periods are produced at the field station and measured in the control office.

15 When the control office places an impulse on the line of either polarity, it opens the line circuit at the end of the impulse. As soon as the line is opened, the field station either closes it or holds it open dependent upon the indication to be transmitted. The control office makes a test of the line by closing it. If the line tests open (due to the field station having an indication requiring a long open period) the control office immediately opens the line again 20 and holds it open for a comparatively long interval. During this interval the field station closes the line but the line circuit is not energized because of its open condition in the office. The line circuit is finally energized after the 25 lapse of the long time interval measured by the control office.

On the other hand, if the line is left closed at the field station subsequent to its being opened by the control office, then when the control office tries to close it for the next impulse it is immediately energized. In other words, the control office tries to close the line and if it is successful a short deenergized period is the result; but, if it is not successful until the second trial, 40 a long deenergized period is the result.

The organization of a communication system in accordance with the present invention, as above outlined, gives a distinct advantage in that the timing of the spaces or time intervals 45 between successive impulses applied to the line circuit at the control office is determined by a single timing means located in the central office. The means at the several stations which cause time spaces to be prolonged may vary in their 50 total time of effectiveness, but this is immaterial so long as their minimum time of effectiveness is sufficiently long to initially cause the control office to delay a time space for an added period of time, as such added time is sufficient to allow for 55 the variations at the several stations. Thus, the total time which the line circuit is open is determined in the control office instead at the several stations.

This system employs the superiority of code 60 arrangement for dropping out all field stations except the one having a superior code when an attempt is being made to transmit indications from more than one field station at the same time.

65 *Control office apparatus.*—As typical of the control means located in the control office and associated with each field station, a control lever SML is indicated in Fig. 1. A code determining relay CD associated with each station is used for 70 connecting the variably connected code jumpers and the levers to the selecting circuits. A bank of station registering relays of conventional arrangement is indicated by reference characters PT¹, PT² and PT³. These latter relays are 75

operated by code signals when a station is to be selected for transmission of indications. They are positioned one at a time in accordance with the position of relay K, the latter relay being provided for the purpose of storing over from one period until the next executing period the condition which is to be used for positioning the PT relay (with suitable exponent).

The embodiment of the present invention utilizes the first three steps of the cycle for station selection on outbound cycles as well as for registering the stations on inbound cycles. A fourth step is utilized to select control and indication devices after station selection and registration. It is apparent that more than three steps may be provided to select more stations and that more than one step may be provided to select more controls and indications. A station to be registered for transmission of indications will cause the operation of one or more of the three PT relays in combination after which a station relay ST will be actuated on the fourth step. At this fourth step an indication relay such as IN may be positioned to light an indication lamp such as I.

A bank of four stepping relays 1V, 2V, 3V and 4V is shown with their associated repeating or half step relay VP arranged in a manner to be energized in sequence on the open periods following the impulses in the line circuit. It is obvious that additional stepping relays would be used for selection in a system of larger size. The eight wires leading from the contacts of relay PT³ adjacent bracket A may be connected to additional station relays similar to ST, one for each station, thus indicating that eight code combinations are possible. By providing one more stepping relay for station selection it is obvious that another PT relay could be added, thus doubling the number of available stations by further pyramiding the contacts of the PT relays.

A code sending relay CS provides for selecting the polarity of the battery to be applied to the line in accordance with the code impulses required when transmitting controls. Relay K is provided for selecting the polarity of the battery to be applied to the PT relays for registering a station as well as applying this battery to the polar indicating relays IN for positioning them properly to display the required indications.

Slow operating and slow releasing cycle demarcating relays SA and SAP are provided to define the bounds of an operating cycle and to insure synchronism of the system at the beginning of each cycle. Relay C is used both as a cycle control relay and for checking the particular deenergized condition which exists as each step. This relay operates to start the cycle of operations as well as to register whether the open or deenergized condition of the line between impulses is long or short.

A three position, polarized, biased-to-neutral, line relay F is connected in the line circuit and is normally energized by current which is normally applied to the line. Relay FP is the line repeating relay and it follows the operation of relay F, that is, relay FP is energized when relay F is in either one of its actuated positions and is deenergized when relay F is in its neutral position.

Impulsing relay PL is provided for opening the line circuit at the control office. This relay is controlled by impulse marking relay E associated with the stepping relay bank, relay E being used

to mark off the steps for energizing relay PL at the proper time. J and JP are quick operating and slow releasing relays used to prolong the de-energized period between impulses in the line circuit when the indication requires it. EB is an auxiliary relay used to prepare the circuit for operating relay C to register the requirement for a long open period.

Field station apparatus.—The traffic controlling devices located at the field stations may vary according to local conditions and for example, may comprise two-position polarized relays similar to SMR actuated to the proper position for controlling the signals. Track relay T and other relays such as relay WP record different conditions requiring transmission to the control office.

At each field station a line relay F¹ and a line repeating relay FP¹ are provided and operate in a manner similar to corresponding relays in the control office for governing the operation of the cycle demarcating relays SA¹ and SAP¹. The F¹ and FP¹ relays also control the fast operating, slow releasing relay J¹ and other circuits as will be described in detail. Two station selecting relays SO and SI are provided. SO is the relay used to select the particular station for outbound signals or transmission of controls and SI is used to select a particular station for inbound signals or transmission of indications. An auxiliary station selecting relay SOS is provided for a purpose which will be described in detail. The stepping relay bank including the four stepping relays and the half step relay comprises an arrangement similar to that used in the control office, these relays being identified by reference characters corresponding to like relays in the control office, but with the exponent (1) added. Like the stepping relays in the control office they are actuated on the open period of the line circuit between impulses.

A change relay CH is indicated but its complete control circuit is not shown. It will be understood that additional relays and contacts are connected in a manner similar to the contacts of relay T and wired in a series circuit so that any change in condition causing one of these contacts to switch from front to back will momentarily open the stick circuit of relay CH and allow it to release. The complete circuit arrangement for this CH relay may be similar to that disclosed in the patent to DeLong et. al., 1,852,402, and to simplify the present disclosure this circuit will not be shown or described in detail.

The equipment at each field station, as well as that in the control office, such as groups of associated relays, may be grouped into suitable cabinets and arranged for ease in removal for replacements or testing purposes. Various other devices and apparatus which are necessary in railway signalling practice such as terminal blocks and connections, and lightning protective equipment may also be provided but have not been indicated in this disclosure.

DETAILED OPERATION

With the communication part of the centralized traffic controlling system with which this invention is concerned at rest, all of the relays in the control office are in their normal or de-energized positions except relays F, FP, J and JP. Relay F is normally positioned to the left by current flowing from the (+) terminal of battery B, back contact 1 of relay CS, upper line conductor, through the normally closed back contacts similar to 102 of the PL relays at all

the field stations in series, windings of all the F relays at the field stations, including the winding of relay F^1 , over the lower side of the line, back to the control office, through back contact

5 3 of relay PL in the control office, winding of relay F and back contact 4 of relay CS to the (—) terminal of battery B.

With relay F positioned to the left, a circuit is closed for energizing relay FP extending from 10 (+), contact 5 of relay F and winding of relay FP, to (—). Relay J is normally energized over a circuit extending from (+), front contact 6 of relay FP and winding of J, to (—). Relay JP is normally energized over a circuit extending 15 from (+), front contact 7 of relay J and winding of JP, to (—). A circuit in multiple with contact 7 is completed by front contact 8 of relay FP for energizing JP, this circuit arrangement for energizing J and JP at front contacts of relay FP and for establishing an additional energizing circuit for JP at a front contact of J, being 20 for the purpose of quickly actuating both of these relays simultaneously and for deenergizing them in sequence for providing a long time interval 25 upon release.

The current in the above traced circuit, extending through relay F^1 at the field station, positions this relay to the left and it in turn completes a circuit for energizing J^1 , extending from 30 (+), contact 105 of relay F^1 , back contact 106 of relay SAP¹ and winding of J^1 , to (—). It will thus be seen that relays F^1 and J^1 at the field station shown in Fig. 2 are normally energized. Likewise, the line relays such as F^2 , as well as relays similar to J^1 at other field stations are energized when the system is at rest.

The track relay T is energized when no train is upon the detector track section. This circuit arrangement of relay T is not shown in detail, 40 since it is now well known how it may be connected to the track for indicating the presence or absence of traffic thereon.

The system is initiated into a cycle of operations by momentarily opening the line circuit, either at the control office or at any field station 45 by means later described. A cycle consists of a definite number of impulses connected to the line at the control office and during this cycle, controls may be transmitted from the control office to select any one of the field stations and to position the controlling devices at the field stations. Indications may also be transmitted from any field station to the control office during this cycle. If the cycle of operations is initiated at 50 the control office a CD relay will be actuated by the operation of an associated starting button SB. The complete operating circuits for the CD relays have been omitted for the sake of simplifying the drawings but, as has been mentioned, only one CD relay can be picked up at one time. After a cycle has been started by indications being sent in from a field station, no CD relay in 55 the control office can be picked up until the end of this cycle. This operation of the CD relays 60 may be similar to the arrangement disclosed in the above mentioned application, Ser. No. 455,-304.

The short oblique connections to all the wires attached to contacts at the right of the CD relay, as well as any other wires having this indication, means that these are common connections. There are several CD relays, one for each station and the common wires shown connected to the contacts of the CD relay illustrated in Fig. 70 75 1 also connect to the corresponding contacts of

other CD relays which are not shown. Those wires without this indication lead to jumpers, contacts or the like which are individual to the relay.

For convenience in describing the operation of the system, an operating cycle is divided into the following periods: 1st, line closed, normal; 2nd, line open, start; 3rd, line closed, preliminary impulse; 4th, line open, first stepping relay picked up, first indication code registration; 5th, line closed, first control code registration; 6th, line open, second stepping relay picked up, second indication code registration; 7th, line closed, second control code registration; 8th, line open, third stepping relay picked up, third indication 15 code registration; 9th, line closed, third control code registration; 10th, line open, fourth stepping relay picked up, fourth indication code registration; 11th, line closed, fourth control code registration.

Transmission of controls alone.—It will be assumed that the system is at rest or in its normal period and that the operator desires to transmit controls to the field station indicated in Fig. 2. This field station is selected by an outbound 25 code combination (+)(+)(—) as indicated by the code jumper connections 138, 145 and 149 associated with the two upper sets of contacts of the stepping relay bank. The particular CD relay illustrated in Fig. 1 applies this code combination (+)(+)(—) to the system, as indicated by code jumper connections 55 and 56 connected to contacts of the CD relay. After the switch machine lever SML and signal levers (not shown) are positioned, starting button SB, associated 30 with the desired station, is actuated to close a circuit (not shown) for picking up the CD relay. A stick circuit is now completed for CD extending from (+), back contact 9 of the final stepping relay (not shown), front contact 11 of relay CD and lower winding of CD, to (—). This 35 stick circuit maintains CD in its operated position until the end of the cycle, as will be more fully pointed out later.

Relay CD closes a circuit from (+), through its front contact 13, back contact 14 of relay SAP 45 and upper winding of relay C, to (—). It may be noted here that, since the wires attached to contact springs 13 are indicated as being common, the operation of any CD relay in the group 50 closes this circuit for operating the C relay, which is effective to start the cycle of operations. Relay C is picked up and stuck up over a circuit extending from (+), front contact 15 of relay JP, front contact 16 of relay C and lower winding of 55 relay C, to (—). The operation of the C relay closes a circuit for operating relay PL extending from (+), front contact 17 of relay C and winding of PL, to (—). Relay PL closes a circuit for operating relay EB extending from (+), 60 front contact 18 of relay PL and winding of relay EB, to (—). Relay EB has no function in connection with transmission of controls and its purpose will be described in connection with transmission of indications. The operation of 65 relay PL opens, at its back contact 3, the line circuit which carries the operation into the start period and releases relay F in the control office, relay F^1 at the station indicated in Fig. 2 and other relays similar to F^2 at all field stations.

The release of relay F in the control office opens the circuit of relay FP allowing the latter relay to release, while the release of relay F^1 at the field station closes a circuit for energizing relay SA¹ extending from (+), back contact 107 of 70 75 75

5 relay SAP¹, contact 108 of relay F¹ and winding of relay SA¹, to (-). The operation of relay SA¹ closes a circuit for operating relay SAP¹ extending from (+), front contact 109 of relay SA¹ and winding of relay SAP¹, to (-).

When relay SA¹ operates and before the operation of relay SAP¹, a circuit is closed for operating relay SO extending from (+), front contact 111 of relay SA¹, back contact 112 of relay SAP¹ 10 and lower winding of relay SO, to (-). Relay SO completes a stick circuit for itself extending from (+), front contact 111 of relay SA¹, back contact 113 of relay FP¹, front contact 114 of relay SO and upper winding of relay SO, to (-). 15 It will be understood that this series of operations occurs at all field stations so that at this time all SO relays are energized.

In the control office the release of relay FP closes a circuit for actuating relay SA extending from (+), back contact 21 of relay FP, back contact 22 of relay SAP and winding of relay SA, to (-). A substitute circuit around contact 22 is established by contact 23 of the SA relay while it is energized. A circuit is now completed for actuating relay SAP extending from (+), front contact 24 of relay SA and winding of relay SAP, to (-).

A circuit is completed at this time for operating relay CS extending from (+), front contact 25 of relay CD, back contacts 26, 27, 28 and 29 30 in series of the four stepping relays, front contact 31 of relay SAP and lower winding of relay CS, to (-). Since contact 25 is connected in multiple to all CD relays, the operation of any 35 one of these relays establishes the circuit for energizing relay CS. The operation of the CS relay reverses the battery connected to the line circuit by switching contacts 1 and 4. At this time however, the line circuit is open so this has no effect on the F relays.

The first open period of the line is of comparatively long duration and is used to start the cycle of operations. This long time interval is obtained by releasing the J and JP relays in sequence. 40 When the FP relay was released as above described, the circuit which normally held relay J energized was opened at front contact 6 of relay FP. After a predetermined time interval, relay J drops and at its front contact 7 opens the energizing circuit of relay JP, and after an additional predetermined period of time, relay JP is released. The release of relay JP closes a circuit for operating relay K extending from (+), back contact 15 45 of relay JP and lower winding of relay K, to (-). The release of relay JP also opens at its front contact 15, the stick circuit of relay C, allowing this latter relay to drop. When relay C drops, it opens at its front contact 17, the circuit of relay PL, this latter relay is de-energized and the line 50 circuit in the control office is closed for the preliminary impulse period.

Again referring to the field station circuit, the restoring of relay F¹ to its neutral position by opening the line circuit as above described, opens at contact 105 the energizing circuit of relay J¹, 55 allowing this latter relay to deenergize after an interval of time substantially the same as the time required for releasing relay J in the control office. It will be noted however, that relay J¹ will be released before relay JP is released.

The above operations at the control office and at the field stations have been effective to start the cycle of operations by opening the line in the control office, conditioning certain relays and again closing the line in the control office. The 75

line is energized at the time the control office makes the preliminary impulse closure due to relays PL¹, PL², etc., at the stations being deenergized. This is because no indications are to be transmitted at this time.

The line circuit being now energized, again picks up relay F in the control office, and over a circuit extending through contact 19 of relay F, relay FP is again actuated. The release of relay PL, above described, also opened the circuit of 10 relay EB allowing this latter relay to drop away. Relay F is actuated to its right hand position, because relay CS is energized, and reverses the current flow over the line conductors, causing this current to be in the opposite direction from normal. This impulse is made (+), at the start of each control or duplex cycle irrespective of the code combination associated with the desired station, for the purpose of energizing the SOS relay at the station and maintaining its associated SO 15 relay in its energized condition at this time. It will be understood that one-half of the code combinations used for selecting stations will begin with (-), therefore, it is necessary to provide a preliminary (+), to condition the SOS relay before the first code impulse is applied to the line.

The energized line circuit is also effective to again energize relay F¹ and this relay closes a circuit from (+), its contact 115, front contact 106 of relay SAP¹, front contact 116 of relay SO 30 and winding of relay FP¹, to (-). Relay F¹ closes a circuit for operating SOS extending from (+) front contact 117 of relay SO, contact 118 of relay F¹, now in its right hand position, back contacts 119, 120, 121 and 122 of the four stepping 35 relays in series, lower winding of relay SOS and lower winding of relay SO, to (-). This circuit also maintains relay SO in its actuated position and the operation of relay SOS establishes an additional circuit to stick the SO relay, extending 40 from (+), front contact 123 of relay SOS, front contact 114 of relay SO and upper winding of relay SO, to (-). Relay SOS is also stuck up through its upper winding and its front contact 137, front contact 113 of relay FP¹ and front contact 45 111 of relay SA¹, to (+).

Again referring to the control office circuit, the actuation of relay FP closes a circuit for operating relay J and this relay in turn establishes the circuit for energizing relay JP, as has already been 50 described. From this point on until the start of another cycle the impulses follow each other in rapid succession and the open periods between impulses are of short duration so that the J and JP relays do not drop away. The closed periods 55 are also short so that relays SA and SAP do not release. The operation of relay FP establishes a stick circuit for relay K extending from (+), front contact 32 of relay SAP, front contact 33 of relay FP, front contact 34 of relay K and upper 60 winding of relay K, to (-).

Relay FP also closes an energizing circuit for the VP relay extending from (+), front contact 35 of relay SAP, front contact 36 of relay FP, back contact 37 of relay IV, and winding of relay VP, 65 to (-). Relay VP establishes a substitute branch of the above described circuit, from contact 35 of relay SAP and front contact 38 of relay VP, over the remainder of the above described circuit, to the winding of VP. This substitute circuit is for 70 the purpose of maintaining VP in its energized position, irrespective of the operation of FP, as long as relay IV is de-energized.

Again referring to the field station, the actuation of relay FP¹ above described, closes a circuit 75

for actuating relay J^1 , extending from (+), front contact 124 of relay FP^1 and winding of relay J^1 , to (-). The half step relay VP^1 at the station is now actuated over a circuit extending from (+), 5 front contact 125 of relay SAP^1 , front contact 126 of relay FP^1 , back contact 27 of relay IV^1 and winding of relay VP^1 , to (-). Relay VP^1 is likewise held energized over a branch circuit extending through contact 128 of relay VP^1 , in order that 10 this relay will remain actuated irrespective of the switching over of contacts 126 of relay FP^1 , as long as the first stepping relay IV^1 is de-energized.

Referring back to the control office, the actuation of relay VP closes a circuit for operating relay 15 E extending from (+), back contacts 41, 42, 43 and 44 of the four stepping relays in series, lower winding of relay E and front contact 45 of relay VP , to (-). Relay E closes an operating circuit for relay EB extending from (+), front contact 20 39 of relay E and winding of relay EB , to (-). Relay E also closes an operating circuit for relay PL extending from (+), front contact 46 of relay E and winding of relay PL , to (-).

This actuation of relay PL opens at its contact 25 3, the line in the control office, allowing relays F and FP to be released. This is the period during which the first stepping relay is picked up. Relays F^1 and FP^1 at the station are likewise released. The release of relay FP in the control office closes 30 a circuit which picks up the first stepping relay IV , extending from (+), front contact 32 of relay SAP , back contact 33 of relay FP , front contact 47 of relay VP , back contact 48 of relay IV^1 , back contact 49 of relay $2V$ and winding of relay IV , to (-). Relay IV is stuck up until the end of the cycle through its own front contact 51, stick conductor 2 and front contact 52 of relay SAP , to (+). Relay VP is now maintained in its energized condition over a circuit extending from (+), 35 front contact 35 of relay SAP , back contact 36 of relay FP , front contact 53 of relay VP and winding of this relay, to (-).

Relay IV^1 at the station is actuated at substantially the same time as relay IV in the office, 40 over a circuit extending from (+), front contact 125 of relay SAP^1 , back contact 129 of relay FP^1 , front contact 131 of relay SO , front contact 132 of relay VP^1 , back contact 133 of relay $4V^1$, back contact 134 of relay $2V^1$ and winding of relay IV^1 , to (-). Relay IV^1 is stuck up until the end of the cycle over a circuit extending from (+), front contact 125 of relay SAP^1 , stick conductor 103 and front contact 135 of relay IV^1 . Relay VP^1 is now held in its energized condition over a circuit 45 extending from (+), front contact 125 of relay SAP^1 , back contact 126 of relay FP^1 , front contact 136 of relay VP^1 and winding of this relay to (-). The operation of relay IV^1 opens the original operating circuit of relay SOS at back contact 122 of IV^1 . Since relay FP^1 is now down, the stick circuit through contact 137 of relay SOS is broken and this relay drops. Relay SO is stuck up at this time through its front contact 114, back contact 113 of relay FP^1 and front contact 50 111 of relay SA^1 , to (+).

Referring back to the control office, the dropping of relay FP opens the stick circuit of relay K and this latter relay de-energizes. The picking up of the IV relay opens the circuit of relay 55 E at back contact 44 of relay IV allowing relay E to drop and it in turn allows the PL and EB relays to release.

The release of relay PL again closes the line circuit at its contact 3 for the first control code 60 period and relays F and FP are again picked up

over the circuits above described, the circuit of relay FP being closed at contact 19 of relay F because relay CS is up for a reason which will now be explained. The previously traced circuit for picking up the CS relay through back contact 5 26 of relay IV is broken when relay IV is operated. Relay CS may be de-energized momentarily but will be immediately picked up over a circuit extending through front contact 26 of relay IV , front contact 54 of relay CD and code jumper 55, to (+). This circuit will be effective 10 to get relay CS up before relay PL drops and closes the line circuit at its contact 3, thus connecting battery B to the line in such a direction that relays F and F^1 are positioned to the right. 15

Jumper 55 is connected to complete the circuit of front contact 54 of relay CD to (+), since the first impulse is (+) because the assumed desired station has a code combination (+)(+) (-). Code jumper 56 is likewise connected since 20 the second impulse is assumed to be (+), but the code jumper associated with front contact 57 of relay CD is not connected, since the third impulse is assumed to be (-). Therefore, relay CS will be up on the second step and down on the third 25 step. It will be evident that if the first impulse of the code corresponding to a desired station is to be (-), jumper 55 is omitted and if the second impulse is (-), jumper 56 is omitted from the connections leading to the contacts of the CD 30 relay corresponding to such station.

The closure of the line circuit for the first code impulse also picks up relays F^1 and FP^1 at the station and since this is a (+) impulse, relay F^1 will operate to the right closing its contact 115 for 35 operating relay FP^1 . Relay SOS will be energized at this time over a circuit extending from (+), front contact 117 of relay SO , contact 118 of relay F^1 , back contacts 119, 120 and 121 of relays $4V^1$, $3V^1$ and $2V^1$ in series, front contact 122 of relay IV^1 , code jumper 138, control bus 153 and lower windings of relays SOS and SO in series to (-). Code jumper 138 is connected to bus 153 40 at all stations having a code combination beginning with (+). At all stations beginning with (-) this jumper is omitted, so that at this time, at these latter stations the SOS relays are not picked up and since the FP^1 relays are picked up there are no circuits for holding the SO relays at these stations and they release. When an SO relay de-energizes after the start of a cycle, it cannot again be picked up until another cycle starts 45 since its only pick-up circuit is through back contact 112 of relay SAP^1 and this latter relay is down only after a cycle of operation has been completed. It will thus be seen that all stations which were started through the cycle with their SO relays picked up but which do not have a jumper 138, are dropped out at this time and that the SO relays, at front contacts similar to 50 116, open the circuits of relays similar to FP^1 . Front contacts similar to 131 of the SO relays interrupt the circuits of the stepping relays, so that these relays do not go through any further operations during this cycle at stations dropped out. 55

The actuation of relay SOS above described completes at its front contact 123 a stick circuit for the SO relay. A stick circuit for the SOS relay is established at its front contact 137 by way of front contact 113 of relay FP^1 and front 60 contact 111 of relay SA^1 , to (+).

At the control office, the actuation of the FP relay opens, at its back contact 36, the stick circuit of the VP relay, allowing this latter relay to release. The VP^1 relay at the station is likewise 65

dropped at this time due to the fact that relay FP^1 opens, at its back contact 126, the stick circuit of relay VP^1 . The dropping of the VP relay in the office closes a circuit for again actuating relay E , extending from (+), back contacts 41, 42 and 43 of stepping relays $4V$, $3V$ and $2V$ in series, front contact 44 of relay IV , upper winding of relay E and back contact 45 of relay VP , to (-). The operation of relay E again closes circuits above described for energizing the PL and EB relays.

Relay PL opens the line circuit at its back contact 3, allowing the F and FP relays in the control office and the F^1 and FP^1 relays at the station to release, in a manner previously described. This is the period during which the second stepping relay is picked up. The release of relay FP establishes a circuit which operates relay $2V$ extending from (+), front contact 32 of relay SAP , back contact 33 of relay FP , back contact 47 of relay VP , back contact 58 of relay $3V$, front contact 59 of relay IV and winding of relay $2V$, to (-). Relay $2V$ establishes an obvious stick circuit for itself at its front contact 61, to (+) on stick conductor 2.

At the station, relay $2V^1$ is actuated, by the dropping of relay FP^1 , over a circuit extending from (+), front contact 125 of relay SAP^1 , back contact 129 of relay FP^1 , front contact 131 of relay SO , back contact 132 of relay VP^1 , back contact 139 of relay $3V^1$, front contact 141 of relay IV^1 , and winding of relay $2V^1$, to (-). Relay $2V^1$ establishes an obvious stick circuit for itself at its front contact 142, to (+) on stick conductor 103. When relay F^1 restores to its neutral position it opens, at its contact 118, the circuit through the lower winding of relay SOS and the release of relay FP^1 opens, at its front contact 113, the stick circuit of relay SOS so that this relay is de-energized at this time. Relay SO remains in its operated position, due to its stick circuit now being completed through back contact 113 of relay FP^1 .

Again referring to the control office circuit and recalling that the first two stepping relays IV and $2V$ are actuated and that the polarity of the second impulse is (+), due to the fact that code jumper 56 is connected, it will be apparent that relay CS will be actuated at this time, over a circuit previously described, except that it now includes front contact 27 of relay $2V$, front contact 62 of relay CD and the connected code jumper 56, to (+).

The actuation of the $2V$ relay opens the circuit through the upper winding of relay E , at back contact 43 of relay $2V$, allowing E to drop and open the circuits of the PL and EB relays which restores these relays to normal. This again closes the line circuit for the second control code registration period so that current from battery B is effective to again pick up the F and F^1 relays. These relays again energize the FP and FP^1 relays by means of circuits above described. It will be obvious that the F and F^1 relays are positioned to the right since relay CS is actuated, allowing current to flow from the (+) side of battery B , over the lower line conductor, by way of front contact 4 of relay CS , returning to the (-) side of this battery by way of front contact 1 of relay CS .

Relay VP is now actuated over a circuit extending from (+), front contact 35 of relay SAP , front contact 36 of relay FP , back contact 63 of relay $3V$, front contact 64 of relay $2V$ and winding of relay VP , to (-). Relay VP is stuck up

over a circuit independent of the FP relay contact 36, by way of front contact 38 of relay VP , over the remainder of the circuit just described.

At the station, relay VP^1 is now actuated over a circuit extending from (+), front contact 125 of relay SAP^1 , front contact 126 of relay FP^1 , back contact 143 of relay $3V^1$, front contact 144 of relay $2V^1$ and winding of relay VP^1 , to (-). A substitute circuit for relay VP^1 independent of the FP^1 relay contacts is established by way of front contact 128 of relay VP^1 and over the remainder of the circuit just described. Relay SOS is now operated over a circuit extending from (+), front contact 117 of relay SO , contact 118 of relay F^1 , back contacts 119 and 120 of relays $4V^1$ and $3V^1$ in series, front contact 121 of relay $2V^1$, code jumper 145, bus 153, lower winding of relay SOS and lower winding of relay SO , to (-). Relay SOS establishes a stick circuit for itself at its front contact 137 and it also establishes at its front contact 123, a stick circuit for the SO relay, both circuits being previously traced.

Relay E in the control office is now picked up due to the closure of its energizing circuit extending from (+), back contacts 41 and 42 of relays $4V$ and $3V$, front contact 43 of relay $2V$, lower winding of relay E and front contact 45 of relay VP , to (-). The actuation of the E relay again closes circuits for actuating the EB and PL relays, the latter being effective to again open the line circuit. This is the period during which the third stepping relay is picked up. Relays F and FP in the control office and relays F^1 and FP^1 at the station now release. At the control office the third stepping relay $3V$ is actuated, over a circuit extending through back contact 33 of relay FP , front contact 47 of relay VP , back contact 48 of relay $4V$ and front contact 49 of relay $2V$ to the winding of relay $3V$. This relay establishes an obvious stick circuit for itself to (+) on stick conductor 2. Relay VP is maintained in its energized condition at this time due to the extension of (+), through back contact 36 of relay FP and front contact 53 of relay VP to its winding.

The third stepping relay at the station is also actuated at this time over a circuit extending through back contact 129 of relay FP^1 , front contact 131 of relay SO , front contact 132 of relay VP^1 , back contact 133 of relay $4V^1$, and front contact 134 of relay $2V^1$, to the winding of $3V^1$. This third stepping relay completes a stick circuit for itself to (+), which is connected to the common conductor 103, used for sticking all these stepping relays. Relay VP^1 is now maintained in its energized condition due to the connection of (+), by way of back contact 126 of relay FP^1 and front contact 136 of relay VP^1 to its winding. Relay SOS is now dropped because the circuit through its lower winding is open at back contact 120 of relay $3V^1$ and because the circuit through its upper winding is open at front contact 113 of relay FP^1 . The SO relay is stuck up at this time through the back contact 113 of relay FP^1 over the remainder of the circuit previously described.

Referring to the control office, relay CS is down at this time due to the fact that the circuit through front contact 28 of relay $3V$ to front contact 57 of the CD relay is incomplete, since there is no code jumper connection to contact 57. This is due to the fact that the third code impulse is (-), which requires relay CS being in its normal or de-energized condition. This connects battery B to the line conductors in the original direction, which will be effective to position 75.

tion relays F and F^1 to the left when the line circuit is next closed. Relay E is released at this time because the circuit through its lower winding is broken at back contact 42 of relay 3V. The 5 release of relay E again allows the EB and PL relays to drop, the latter relay closing the line circuit for the third impulse, the code for this impulse being assumed (-). This is the third control code registration period.

10 Relays F in the control office and F^1 at the station are now positioned to the left closing circuits for operating associated relays FP and FP^1 . Relay VP in the control office is now restored to normal due to opening its stick circuit at back 15 contact 36 of relay FP. Relay VP^1 at the station is likewise released due to opening its stick circuit at back contact 126 of FP^1 . A circuit is now established for picking up relay SOS extending from (+), front contact 117 of relay SO, 20 contact 146 of relay F^1 , back contact 147 of relay 4V¹, front contact 148 of relay 3V¹, code jumper 149, bus 153 and lower windings of relays SOS and SO in series, to (-). This circuit, in addition to actuating relay SOS, holds the SO relay 25 until relay SOS completes, at its front contact 123, the stick circuit for relay SO. Relay SO again completes its stick circuit, as above described. Relay E in the control office is now actuated over a circuit extending from (+), back 30 contact 41 of relay 4V, front contact 42 of relay 3V, upper winding of relay E and back contact 45 of relay VP, to (-). The circuits for again actuating relays PL and EB are now completed at front contacts of the E relay, the opening of contact 3 of the PL relay opening the line circuit and releasing relays F, FP, F^1 and FP^1 . This is the period during which the fourth stepping relay is picked up. The actuating circuit for the stepping relays, above described, is now 35 extended to relay 4V in the control office, by way of back contact 47 of the VP relay and front contact 58 of the 3V relay. Relay 4V operates and completes a stick circuit for itself including stick conductor 2. Relay 4V¹ at the station is 40 actuated at this time by way of back contact 129 of relay FP^1 , front contact 131 of relay SO, back contact 132 of relay VP^1 , front contact 139 of relay 3V¹ and winding of relay 4V¹, to (-). This latter relay is stuck up over stick conductor 103. 45 Relay SOS at the station is now released, due to the above described operating circuit for this relay being opened at back contact 141 of relay 4V¹ and its stick circuit being incomplete at front contact 113 of relay FP^1 . Relay SO remains stuck up however, through back contact 113 of relay FP^1 .

50 The CS relay in the control office is now actuated if the control to be transmitted, such as switch machine lever SML, is in the proper position for completing the circuit to (+). If this condition exists, then battery B is connected to the line conductors in reverse order from the normal connection, so that relay F^1 will be positioned to the right upon the next closure of the line. It is evident that an incomplete circuit for relay CS at this time results in, what may be conveniently termed a (-) impulse being applied to the line for positioning relay F^1 to the left.

55 The energization of the 4V relay in the control office results in releasing relay E due to opening its energizing circuit at back contact 41 of relay 4V. This results in dropping the EB and PL relays and again closing the line circuit. This is the fourth control code registration period. Relays F, FP, F^1 and FP^1 are again actuated. The

VP and VP^1 relays are picked up over circuits completed at front contact 65 of relay 4V in the office and front contact 151 of relay 4V¹ at the station, respectively. These relays again close their stick circuits by way of their front contacts 5 38 and 128 respectively.

60 Relay SO at the station has its stick circuit now complete at front contact 152 of relay 4V¹. It should be understood that the location of this contact 152 may be varied to suit conditions, for example, if only two steps are used for selecting the station, then this contact would be placed on relay 3V¹, while if six steps were used to select the station, then this contact would be used on the next succeeding stepping relay, which would 15 be the 7V¹ relay. This stick circuit for relay SO is for the purpose of holding it in its operated condition after the station has been selected and during the transmission of controls to the selected station. 20

25 Referring back to the control office, the operating and stick circuits for relay VP have been described for the fourth control registration period. It will be understood how these circuits for the VP relay are extended so that the operation of this half step relay can be continued when additional stepping relays, such for example, as a 5V, 6V etc., are provided. It will be noted that when the last stepping relay is picked up there is no energizing circuit for relay E, 30 therefore relays EB and PL are not again operated and the line circuit remains closed for a comparatively long period. It is obvious that additional stepping relays may be arranged to connect to additional control circuits, similar to 35 the circuit leading to lever SML and these connections may be made on successive steps. This extension of the stepping relay operation has not been shown in order that the disclosure may remain as simple as possible. 40

45 Back contact 9 may be placed on the last stepping relay of the series and this stepping relay may be in addition to the number required to select the desired controls. In this way, relay CD remains in its operated position and maintains the control circuits through its make contacts complete, until after the final step is taken, after all controls have been transmitted. It will be understood that back contact 9 may be placed on stepping relay No. 7 if six stepping relays are 50 provided for station selecting and for transmission of controls. It is also evident that a similar additional stepping relay would be provided at the station to insure synchronism of the system.

55 From the above description, it will be obvious that only one station will have the combination of code jumpers shown in Fig. 2 and this station will be the one that will be responsive to the combination of code jumpers indicated in Fig. 1, when the indicated CD relay is actuated. On the 60 first step when relays similar to 1V¹ at the stations pick up, only the SO relays at stations having a code jumper arrangement which corresponds to the code jumper arrangement associated with the first step in the control office, will 65 be maintained energized. Other SO relays will be dropped at this step. Likewise on the second step there must be a code jumper 145 at a station in order to maintain the SO relay, since the impulse is positive as determined by code 70 jumper 56 in the control office. Those stations not having this combination will be dropped out. Those stations not having a code jumper on the third step corresponding to 149 will be dropped out when this impulse is negative. If a code 75

jumper is connected from front contact 120 of relay 3V¹ to bus 153, then it requires a positive impulse to hold the SO relay.

Assuming that eight combinations may be obtained with three steps, it will thus be seen that on the first step the SO relays at one-half of the stations will be released and those stations are the ones where the first stepping relay jumper connection does not correspond to the impulse predetermined by the jumper connection of the first stepping relay in the control office. Likewise, on the second step one-half of the remaining stations will be dropped out and those dropped will be those whose jumper connections are not in correspondence with the connection at the control office at this step. On the third step only one SO relay will be maintained energized and this will be the one corresponding to the desired station as determined by the complete code combination.

After station selection the operation of additional stepping relays such as 4V¹ at the station, connect (+) over the circuit through contacts 118 and 146 of relay F¹, by way of front contacts 119 and 147 of relay 4V¹ to control relays such as SMR. The positioning of these polar relays SMR depends on the polarity of the impulse placed on the line. For example, if switch lever SML in the control office is positioned to make contact with (+), then relay CS will be actuated, which will cause relay F¹ to be positioned to the right. This completes the circuit through the upper winding of relay SMR which may be assumed to position this relay to the right. If lever SML is in its alternate position, then relay CS will not be energized, relay F¹ will be actuated to the left and relay SMR will be energized through its lower winding, which may position this latter relay to the left. Relay SMR may be the relay which positions the switch machine and it will be understood that additional relays similar to SMR, when provided, connect to front contacts of additional stepping relays to make available more controls. When these relays such as relay SMR are positioned, circuits (not shown but indicated by dotted lines 154 and 155) are completed for operating switch machine or signal devices. These circuits may be similar to those disclosed in the prior patent of S. N. Wight, Patent No. 1,889,457, dated November 29, 1932. The arrows associated with relay SMR indicate that its windings are in opposite directions, so that current through one winding will position its contacts in the opposite position from that by current in the other winding.

From the above it will be seen that after a cycle of operations has been completed, the line circuit is energized, which is effective to condition relay F in the control office to close contact 5 for maintaining relay FP energized. Likewise relays F¹ and FP¹ at the station will be energized. After a short time interval relay SA is released due to its circuit being opened at back contact 21 of relay FP. After an additional short time interval relay SAP is restored to normal, due to its circuit being opened at front contact 24 of relay SA. The release of relay SAP removes (+) from all the stick circuits, which allows the stepping relays in the control office to deenergize. Similar operations are effective at the field station, since relay SA¹ has its energizing circuit opened at contact 108 of relay F¹ and after it releases it interrupts the energizing circuit of relay SAP¹ at front contact 109. At the station however, relay FP¹ is restored to normal when relay SAP¹ breaks its

circuit at front contact 106. Relay SO is dropped due to its stick circuit being opened at front contact 111 of relay SA¹ and at contact 152 of relay 4V¹.

The release of relay SO interrupts, at its front contact 117, the circuit which actuated any of the control relays, such as SMR and the opening of front contact 125 of relay SAP¹ allows the stepping relays to be restored to normal. The system may now be considered in a position of rest or its normal period.

Before proceeding with the description relating to transmission of indications, certain details of operation will be mentioned. Referring back to the portion of the description where the line circuit was first opened to initiate the cycle of operations, it will be remembered that relay K of Fig. 1 was energized and remained in its operated position until the succeeding closure of the line, at the time the preliminary (+) impulse was applied. On the next succeeding opening of the line circuit the release of relay FP opened the stick circuit for the K relay and it was dropped. Relay K has no function at this time since it is only used in connection with the transmission of indications. Although it was energized, the circuits from (B+), and (B-) on its front and back contacts are not extended until after the operation of the first stepping relay. When stepping relay F¹ is picked up, relay FP is down and relay K drops before the circuit from (B+) on its front contact can be completed at front contact 11 of relay FP. The circuit through the back contact of relay K is ineffective to energize any of the PT relays during a cycle of this kind, since this circuit merely shunts the windings of these relays and does not complete a circuit for current flow. Relay K, after being released, does not pick up again during the transmission of controls.

The SOS relay is provided in order to improve the timing in connection with the operation of relay SO. The energizing circuit over control bus 153 for relay SO includes a winding of relay SOS and the operation of relay SOS completes a stick circuit for relay SO. Therefore, when this energizing circuit is interrupted by relay F¹ restoring to normal, it would require the releasing time of two relays in sequence to drop the SO relay. The restoring of relay F¹ to normal opens the circuit of relay FP¹ and the stick circuit through back contact 113 of relay FP¹ is therefore delayed slightly after the pick-up circuit of relay SO is interrupted. By providing this additional relay, an overlap occurs which insures against the undesired release of the SO relay. Upon the next energization of the F¹ relay the circuit for relay SO is closed at contact 118 before relay FP¹ is picked up and back contact 113 is opened, which breaks the previously described stick circuit of relay SO.

Assuming that the last impulse applied to the line is of positive polarity, it is obvious that relay CS will be actuated over the circuit connected to its lower winding at the time the line is opened and the last stepping relay similar to 4V is picked up. Then when the line is closed by this positive impulse, relay CS is stuck up over a circuit extending from (+), front contact 12 of the last stepping relay similar to 4V, front contact 66 of relay FP, front contact 67 of relay CS and its upper winding, to (-). This stick circuit is also completed to (+), at back contact 24 of relay SA in order that, under the above conditions, relay CS will not be deenergized but will remain stuck up after the first mentioned stick circuit through

contact 12 is broken, at the end of the cycle. If relay CS should be released under these conditions, a false initiation of another cycle might take place, due to momentarily opening the line 5 at its contacts 1 and 4. At the start of another cycle this stick circuit, through back contact 24, is broken so that relay CS will be down if the first impulse of the next cycle is (-).

Transmission of indications alone.—Before proceeding with the detailed operation of this feature of the invention, it will be mentioned that the SI relays are picked up at all stations ready to transmit new indications, at the initiation of an operating cycle. The system will go through a cycle 15 similar to the one previously described and during this cycle the SI relays will be dropped out until only the one corresponding to the station having the superior code will remain. At those stations where the SI relays are released, the 20 stepping relay operation is discontinued and the operation of relays similar to FP¹ is discontinued since their circuits are interrupted at front contacts 186 and 156 of relays similar to SI.

It will be noted that all SO relays are picked 25 up at the start of this cycle since their circuits are completed at contacts similar to 111 and 112 of relays SA¹ and SAP¹. It will be recalled that when controls are transmitted, a preliminary (+) impulse is applied to the line before the 30 first stepping relay is operated, which functions to maintain the SO relays in their operated positions during this portion of the cycle. When indications initiate the cycle, however, the first impulse is (-) because no CD relay in the control office is picked up to complete the circuit for 35 energizing relay CS. This (-) impulse positions relay F¹ to the left, picks up the FP¹ relay and at this point there is no circuit for maintaining the SO relays and they are all dropped 40 out.

If an attempt is made to send controls over 45 the system after indications start a cycle of operations, these controls will be stored and will be taken care of at the beginning of other cycles in a manner fully disclosed in the above mentioned application, Ser. No. 455,304. The reason why it is not possible to break into the cycle under this condition, is because a relay CD can only be picked up at the normal period or the 50 interval between cycles when the stepping relays are all released.

Referring to Fig. 2, it will be assumed that this station alone requires a transmission of indications and that some change in the condition 55 of a traffic controlling device or in the occupancy of a track section has effected the release of change relay CH. The release of relay CH may be brought about by a contact similar to 157 of the track relay T being switched from one point to another. Other relays or devices may bring 60 about the momentary opening of the stick circuit of the CH relay to cause its release and when such a relay is released, this condition may be stored by means of a change storing relay such as CHS, disclosed in the above mentioned patent, 1,852,402. It will also be assumed that the station shown in Fig. 2 responds to an inbound code combination of (long, short, long), this being indicated by code jumpers 171, 172 and 65 173 for the first three steps respectively, being connected to indication buses 174 (long), 175 (short), and 174 (long), respectively. This station also causes the system to send the inbound code combination of (long, short, long), due to 70 code jumper 187 preselecting a (long) for the first

indication code, jumper 191 preselecting a (short) for the second indication code and jumper 192 preselecting a (long) for the third indication code. A completed circuit to (+) through one of these jumpers preselects a (long), while an incomplete circuit through one of them pre-selects a (short).

The dropping of the CH relay closes a circuit, at its back contact 158, from (+), start conductor 159, back contact 161 of relay SAP¹, front 10 contact 162 of relay J¹ and winding of relay PL¹, to (-). Relay PL¹ is operated over this circuit and closes a stick circuit for itself extending from (+), its front contact 163, front contact 15 162 of relay J¹ and winding of relay PL¹, to (-). The operation of relay PL¹ closes a circuit for 20 operating relay SI extending from (+), back contact 164 of relay SAP¹, front contact 165 of relay PL¹ and upper winding of the SI relay, to (-). Only the SI relay at this station is picked up under this condition, since relays similar to PL¹ at other stations have not closed the pick-up circuits of the SI relays at these stations, at front contacts similar to 165.

It having been assumed that the system was 25 at normal when this condition was initiated, relays F¹ and F will be in their energized positions and relay FP¹ will be in its normal or deenergized position. This actuation of the PL¹ relay opens, at its back contact 102, the normally closed and 30 normally energized line circuit, which results in dropping the F¹ and F relays, the latter starting the system through its cycle of operations. Since this cycle will function in a manner similar to the one above described for controlling the 35 control office relays F, FP, SA and SAP, as well as the four stepping relays and the associated half step relay in the control office and since the F¹, FP¹, SA¹ and SAP¹ relays as well as the four 40 stepping relays and the half step relay at the 40 station shown in Fig. 2, all function in a manner similar to that above described, this operation 45 will not be explained again in detail. The start period is of long duration as before and the same sequence of operations is effected as above described for this period, except that relays CD and CS in the office are not picked up. Since relay CS is not up during this cycle, all of the 50 impulses applied to the line during its closed periods will be (-). The same operations occur at the station as before, except that relay CH 55 is down and relays PL¹ and SI are up. Relay PL¹ closes a stick circuit for relay SI extending from (+), front contact 109 of relay SA¹, front contact 166 of relay PL¹, front contact 167 of relay SI and lower winding of relay SI, to (-). During this start period the line is opened and 60 relay J¹ is released, which effects the release of relay PL¹ to close the line circuit at the station but the line is still open at the office, because both the J and JP relays have not released in sequence within the time interval required to release J¹, so that relay C is still up and it maintains relay PL energized, holding the line circuit open at its back contact 3. After relays PL¹ and 65 J¹ at the station are released, relay SI is stuck up over a circuit extending from (+), front contact 109 of relay SA¹, back contacts 110, 176, 177 and 178 of stepping relays 4V¹, 3V¹, 2V¹ and 1V¹ in series, indication bus 174, front contact 167 70 and lower winding of relay SI, to (-). This stick circuit maintains relay SI in its operated condition until the first stepping relay 1V¹ is picked up.

As was previously pointed out, indication codes 75

are provided at field stations by selecting the length of time between impulses that are placed on the line at the control office. Since the first open period is used to start the cycle of operations and since this interval is a comparatively long one, it is evident that this first opening of the line circuit can not be used as a portion of the code combination.

The release of the PL¹ relay at the station 10 closes the line circuit, at its back contact 102, but the line is not energized until relay PL in the office is released to complete the closure of the line, at its back contact 3. This preliminary impulse period is effective to energize the J and 15 JP relays in the office and the J¹ relay at the station by means of circuits previously described. Relay PL¹ is actuated at this time over a circuit extending from (+), code jumper 187, back contacts 168, 169, 188 and 189 of the four stepping 20 relays in series, front contact 179 of relay SI, front contact 181 of relay FP¹, front contact 161 of relay SAP¹, front contact 162 of relay J¹ and winding of relay PL¹, to (-). Relay PL¹ establishes the above described stick circuit for 25 itself, but at this time it does not open the line at its contact 102, because relay FP¹ is picked up and its front contact 182 bridges back contact 102. Relay SI is stuck up at this time by way of front contact 166 of relay PL¹, over the stick 30 circuit previously described.

The line circuit is opened when relay PL, in the control office, is actuated during the preliminary impulse period. This open condition of the line circuit is the first indication code registration 35 period and functions to pick up the first stepping relay IV¹, in the office and the first stepping relay IV¹, at the station. Relay PL¹ at the station, having been actuated as above described, and since relay FP¹ will be released during this open 40 period, the dropping of relay PL in the office fails to energize the line circuit by closing its back contact 3. It is open at contacts 102 and 182 of relays PL¹ and FP¹, respectively, at the station.

At the time relay PL in the office, in releasing, 45 attempts to close the line and fails, it opens, at its front contact 18, the circuit of relay EB allowing this relay to release. A circuit is now established for picking up relay C, extending from (+), front contact 15 of relay JP, back contact 50 68 of relay EB, contact 69 of relay F and upper winding of relay C, to (-). Relay C is stuck up by means of its stick circuit extending to the front contact 15 of relay JP. The picking up of relay C closes a circuit, at its front contact 17, which again picks up relay PL and it in turn 55 closes a circuit, at its front contact 18, which operates relay EB.

Relays C, PL and EB are now held operated and the line is maintained in its open condition 60 until sufficient time has elapsed to drop relays J and JP in sequence. During this time interval relay J¹ at the station will be released, and, at its front contact 162, the circuit of relay PL¹ will be opened allowing this relay to drop but relay PL¹ 65 cannot energize the line circuit, at its back contact 102 at this time, because the circuit is open in the office. Relay SI is now stuck up over a circuit extending from (+), front contact 109 of relay SA¹, back contacts 110, 176 and 177 of stepping relays 4V¹, 3V¹ and 2V¹ in series, front 70 contact 178 of relay IV¹, code jumper 171, indication bus 174, front contact 167 and lower winding of relay SI, to (-). It will be understood that those stations which have a code combination 75 with a long open period on this first step,

will be provided with code jumpers similar to 171 and 187, the former being effective to hold the SI relays in their operated conditions at those stations, and the latter being effective to make this period long. Also at those stations not supplied with code jumpers similar to 171 and 187, when the period corresponding to the first step is long, there will be no circuit to maintain the SI 5 relays and they will drop out.

When relay JP in the office releases, the release 10 of relays C, PL and EB is effected and the next closure or energized period of the line occurs to pick up the F, FP, J, JP, E, PL and EB relays and to drop the VP relay in the control office, all of which has been previously described in connection with this similar first control code registration period, during transmission of controls. During this closed condition of the line circuit as well as others which follow, relays F¹ and FP¹ 15 at the station are picked up and relay VP¹ is released. Relay J¹ is also actuated and this relay as well as the J and JP relays in the office remain in their operated positions throughout the cycle until another long code impulse is required.

It was assumed that the second inbound code 20 impulse is short, therefore, when the line circuit is opened for picking up the first stepping relays during the first indication code registration period, relay PL¹ at the station is not operated, due to the fact that front contact 168 of relay 25 1V¹ and code jumper 191 are not connected to (+). With relay PL¹ down at the station and relay PL down in the office, the line is energized by battery B, and relay F opens its contact 69 before relay EB drops and closes its contact 68. 30 Therefore, the circuit for picking up relay C is incomplete and the line will be immediately re-energized, thus resulting in a short open period for the second indication code. This energization of the line brings the system into the second control 35 code registration period.

On this step, at stations having a code jumper 40 similar to 172, the connection to (+), on conductor 183 is extended through front contact 171 of relay 2V¹, jumper 172 and through front contact 184 of relay J¹, to the stick circuit of the SI 45 relay. This maintains the SI relays in their operated positions at these stations, while at those stations not having this jumper, the stick circuits for the SI relays are incomplete and they are 50 dropped out.

At the third indication code registration period, the line circuit will be held open for another long interval, since it was assumed that the final impulse of the station selecting code is a long one. 55 This long open period is preselected at the time the 2V¹ relay is operated, by way of the circuit extending from (+), code jumper 192, front contact 169 of this relay and over the remainder of the circuit previously described for picking up 60 and sticking relay PL¹. After the 3V and 3V¹ relays are operated, the same sequence of operations takes place as above described for the previous long code and relay SI at the station shown in Fig. 2 is held by means of (+) on conductor 65 183, being extended through front contact 176 of relay 3V¹, code jumper 173, indication bus 174 and the previously described stick circuit of the SI relay. At the station or stations where this code jumper is not provided, the SI relays will be 70 dropped out. The line will now be closed for the third control code registration period, after which it will be again opened to bring the system into the fourth indication code registration period.

If, at the time relay 3V¹ was operated, an indi- 75

- cation relay such as A¹ had established a circuit by way of its contact 185 to apply (+) potential to the make contact 188 of relay 3V¹, then relay PL¹ would have been preconditioned to register another long open code signal during the fourth indication code period, or if there is no circuit completed at the make contact 188 of relay 3V¹ for energizing relay PL¹, then a short open code signal would be recorded. It will be obvious that other steps in addition to those shown may be arranged to select other indicating devices in rotation, similar to that indicated by reference character A¹. Front contact 110 of relay 4V¹ (or the next succeeding stepping relay after the last station selecting step) holds the selected SI relay operated during indication selection and transmission. The circuit through the upper winding of relay CH of Fig. 2, extending from (+), front contact 193 of relay SI, back contact 194 of relay 4V¹ and front contact 195 of relay 3V¹ is for the purpose of restoring this relay, after station registration has been accomplished, following the release of the CH relay which started the cycle of operations.
- If several stations have indications to be transmitted at one time, the PL¹ relays at all of those stations will be picked up and the stepping relays at all such stations will start operating in synchronism. As will be later described in connection with the superiority of code operation, only one of the stations under this assumed condition will remain in connection with the circuit throughout the cycle. The stepping relays are not continued in operation at stations dropped out because their circuits are opened at contacts similar to 186 of the SI relays. Similarly, relays corresponding to FP¹ at stations dropped out do not follow the impulses since their circuits are opened at contacts similar to 156 of the SI relays.
- Since it has been described how the stepping relays in the control office and in the station are operated in synchronism during a cycle of operations, it will now be assumed that those in the control office are picked up one at a time and the registering of the station, as well as the registration of indications from the registered station, will be explained. During the periods when the line circuit is closed following the operation of each of the first three stepping relays, circuits are completed to relays PT¹, PT² and PT³ respectively. These circuits extend from (B-) or (B+) at the lower contacts of relay K, front contact 71 of relay FP and front contact of the operated stepping relay. In the case above assumed, the station having indication code (long, short, long) is registered.
- During the first indication code registration period it may be assumed that relay 4V is up. Relay K is picked up when relay JP is dropped by means of a circuit extending from (+), back contact 15 of relay JP and lower winding of relay K, to (-). When relay FP is picked up in the next or first control code registration period, it closes a stick circuit for relay K extending from (+), front contact 32 of relay SAP, front contact 33 of relay FP, front contact 34 and upper winding of relay K, to (-). Relay FP also completes a circuit for operating relay PT¹ extending from (B+), resistance coil 74, front contact 72 of relay K, front contact 71 of relay FP, back contacts 18, 81 and 82 of stepping relays 4V, 3V and 2V in series, front contact 83 of stepping relay 1V and upper winding of relay PT¹, to (-). Relay PT¹ is stuck up over a circuit

including its lower winding, and its front contact 73 to (+), at front contact 35 of relay SAP.

During the second indication code registration period relay FP is released, opening at its front contact 33, the stick circuit for relay K allowing this latter relay to release. Since this indication code is a short open period, relay JP will not be released at this time and K will not be picked up. Relay 2V is operated during this period and in the following period when relay FP is picked up the circuit from (B-) through back contact 72 of relay K is ineffective to operate relay PT², since it merely shunts the winding of this latter relay. Relay PT³ is picked up on the closed period following the third indication code registration period, over a circuit extending from (B+), resistance coil 74, front contact 72 of relay K, front contact 71 of relay FP, back contact 78 of relay 4V, front contact 81 of relay 3V and upper winding of relay PT³, to (-). Relay K is up at this time because the third indication code registration period is long which allows the JP relay to release.

During the fourth indication code registration period, relay ST is picked up and stuck up in multiple with relay 4V over the previously described circuit which operates 4V, which circuit is extended by way of conductor 94, front contact 75 of relay PT¹, back contact 76 of relay PT², front contact 77 of relay PT³ and winding of relay ST, to (-). Relay ST registers, in the control office, the selection of the station with an indication code combination which is (long, short, long). It will be apparent that other combinations of long and short open periods between impulses may be used to pick up other combinations of the PT relays and that the operation of these relays will function to select other ST relays, corresponding to other stations, when these additional ST relays are individually connected to the wires leading to bracket A. It may be convenient to consider that a long code corresponds to a (+), and a short code to a (-), since the former is effective to pick up relay K and it applies (B+) to the PT and the IN relays while a short code leaves relay K normal for applying (B-) to the pilot and indication relays PT and IN.

After the ST relay is picked up, additional indication codes are effective to position relay K which in turn positions the indication relays, such as IN, by connecting (B+) or (B-) from the contacts of relay K, by way of front contacts 71 and 78 of relays FP and 4V respectively and front contact 79 of relay ST, through the winding of relay IN, to (CN). (CN) indicates an intermediate tap of the battery having terminals (B+) and (B-) so that the position of relay K determines the positioning of relay IN.

The purpose of the stick circuit for relay K extending through front contacts 91 and 92 of relays VP and 4V, is to guard against a possible false operation of an indicating device at the end of a cycle if relay K is up. Without this guard circuit, if K is up when SAP releases, relay K might drop away before relay 4V and close a circuit through its back contact 72 for falsely positioning an indication relay similar to IN. With this guard circuit, relay K is held until either relay VP or relay 4V is dropped after the release of relay SAP.

Superiority of code operation.—Consideration has been given to the condition of only one field station transmitting new indications during an operating cycle. It will now be explained how the system operates in the event that a plurality of

field stations have new indications to transmit, during the same operating cycle. The fundamental requirement is that only one of said field stations can be registered in the control office at 5 a time under this condition and the method of accomplishing this result is similar to the method which is disclosed in detail in the previously mentioned application Ser. No. 455,304.

Those stations having their first code jumper 10 187 in condition for a long deenergized or open line period are superior to those stations which do not have this jumper completed to (+). The reason why such stations are superior is because the line will be open for a long period by stations 15 having an assigned coded arrangement requiring such long open period, in the same manner as if only one station was ready to send in new indications at the beginning of the cycle. This long open period will position the PL¹ relay at 20 the station having an inferior or short open period, so that the stick circuit of the SI relay will not be maintained. The SI relay is therefore down during the remainder of the cycle at the inferior station or stations, thereby preventing 25 the operation being continued at those stations, because the circuit for conditioning the PL¹ relay is broken at front contact similar to 179 of the SI relay.

The next open period in the line is coded by 30 the remaining effective stations in the same manner, that is, if more than one station remains, due to the code jumpers similar to 187 being completed to (+) at said stations, then during the period when relay 1V¹ connects the PL¹ 35 relay to code jumper 191, superior stations will have their circuits established for maintaining their SI relays, while inferior stations cause the release of the SI relays. Likewise when the 2V¹ relay extends the circuit of relay PL¹ to code 40 jumper 192, since this is the last coding period of the cycle, only one SI relay will remain in its operated condition for completing station selection.

As an example, it may be assumed that two 45 stations have new indications to transmit at the beginning of an operating cycle. It will be assumed that station No. 1 has an indication code (long, short, long) and that station No. 2 has an indication code (long, long, long). As above 50 pointed out, station No. 2 is superior to station No. 1, since its code consists of all long periods. After the start of the cycle the PL¹ relays of both these stations are picked up because code jumper 187 is connected to (+) at both stations. 55 This condition causes the first indication code registration period to be long. The SI relays at these two stations will be maintained in their operated positions when the PL¹ and J¹ relays at these stations release, because of the completed 60 stick circuit for these SI relays by way of code jumper 171 and indication bus 174.

During the second indication code registration period, relay PL¹ at station No. 2 above assumed, is picked up since, at this station, code 65 jumper 191 will be connected to (+), but at station No. 1 the PL relay will not be picked up, since the code jumper corresponding to 191 is not connected to (+). The picking up of a PL¹ relay at a station at this time requires that the 70 second indication code registration period be long. This is evident because any PL¹ relay operating, opens the series line circuit which causes the control office to apply a long open period.

The 2V¹ relays are picked up during this period 75 and at station No. 2 (with a long code) the stick

circuit for the SI relay is completed after the PL¹ and J¹ relays are dropped, by way of code jumper 172 which is connected to indication bus 174 at this station. At station No. 1, code jumper 172 is connected to indication bus 175 so that there is no stick circuit for maintaining the SI relay in its operated position when relays PL¹ and J¹ are released. If two stations remain with their SI relays up at the third indication code registration period when relay 3V¹ is picked up, then only 10 one of these stations will continue, since there will be only one of those reaching this point which will have a jumper corresponding to 173 connected to indication bus 174.

Duplex operation.—The manner in which the present disclosure operates to select one of a plurality of field stations and to transmit controls to the selected station when an operating cycle is manually initiated at the control office, has been explained in detail. It has likewise 20 been explained how the system operates to register one of a plurality of field stations in the control office and to transmit indications from the registered station when the cycle is automatically initiated at the station. From the detailed 25 description of the above operations, it will be clear that the selection of a particular field station and the transmission of controls to the selected station are accomplished by selecting the polarity or character of the energized line periods. 30 It will also be clearly understood that the registration of a field station in the control office and the transmission of indications from such a field station are accomplished by the selection of the 35 time intervals between the above mentioned impulses, corresponding to deenergized or open line periods.

Since such transmission of controls and indications take place during separate and distinct 40 conditions of the line, these transmissions are independent of each other and may be incorporated in the same operating cycle when desired. Conditions requiring such simultaneous or two-way transmission of controls and indications occur when controls are stored up at the control 45 office and new indications are stored at one or more field stations at the same time.

The operation of this system for accomplishing two-way or duplex transmission may be understood by assuming that a CD relay in the 50 office and a CH relay at a station are conditioned at the start of an operating cycle requiring transmission of controls and transmission of indications. It is obvious that a number of CH relays at a number of field stations may be positioned for 55 transmitting new indications at the start of a cycle and that a number of controls may be stored in the control office awaiting transmission. In the case of a plurality of controls stored at the control office, it has already been pointed out 60 that they are transmitted in an order determined by the arrangement of the CD relays, so that only one CD relay can be picked up at one time. It has likewise been explained how a plurality of field stations with new indications to be 65 transmitted register themselves at the control office in rotation and in an order determined by the superiority of their code assignments. Since there are no complications involved in operating 70 this system for duplex or two-way transmission, it is not believed necessary to describe the circuit operation during simultaneous transmission of controls and indications. The fact that transmission of controls and transmission of indications occur during the different periods of an 75

operating cycle, as above outlined, indicates that these two transmissions may take place simultaneously, without interference complications.

When it is considered that the controls are transmitted by time spaced impulses of distinctive characters, with the particular control codes determined by reason of the distinctive polarity of the impulses, and that the determination of such polarity is entirely independent of the timing characteristic of the impulses, it is readily apparent that the timing may be varied in accordance with the indication codes to be transmitted from the field stations without in any way affecting the transmission of controls. In other words, the determination of the polarity of any impulses is entirely independent of the time spacing between successive impulses. Thus, the control office can selectively determine the polarity of the impulses simultaneously with the selective determination of the spacing between the impulses from the field stations.

As the operation of the system for the transmission of controls by the selective determination of the polarity of the control impulses has been explained in detail, as well as the selective determination of the time spacing between such impulses for the transmission of indications, and as these different conditions can occur simultaneously without interference, the manner in which the simultaneous occurrence of control transmission and indication transmission may exist is believed to be entirely apparent to one skilled in the art. The operations involved are no different than the operations already described, when a particular station is receiving controls simultaneous with its transmission of indications. The step-by-step mechanism at such a station is the only one which operates all the way through a particular operating cycle; but during a cycle of operation where one station is receiving controls and another station is transmitting indications, then both such stations have their step-by-step means operated throughout such a cycle of operation.

It will be seen that, when the system goes through an operating cycle for transmission of controls, a preliminary (+) impulse is applied to the line before the code impulses are sent. This makes it possible to use all eight code combinations obtained with three steps, without the provision of special circuit arrangements to care for the condition when indications alone are transmitted. When only indications are being transmitted the line is energized with a series of (-) impulses, including the preliminary impulses, which will not be effective to maintain any SO relay energized throughout the series, because without a preliminary (+) they will all be dropped out. Therefore, no special circuit arrangements are required to repeat controls to a station having a code combination of (-)(-)(-) because, even though a station uses this code it will not be selected by an indication cycle of (-)(-)(-). This is due to the fact that such a cycle has a preliminary (-). A preliminary (+) is required to make this code effective.

On the other hand, when controls alone are being transmitted, the same condition for station registration exists as if new indications were being transmitted, that is, the system will send an inbound code combination of (+) and (-) impulses equally spaced which is code (short, short, short). If this code were effective to select a ST relay under this condition, false indi-

cations would result due to the fact that no SI relay would be up to transfer the proper indications to relay K after station registration.

There are two ways of handling this condition; first, not use this inbound code by not connecting wire 87 of Fig. 1 to a ST relay; second, assign this code to a station, connect a jumper wire across terminals X and Y at this station (see Fig. 2) and connect a station relay to wire 87 of Fig. 1. With this arrangement, at the start of each cycle, even if it is for the transmission of controls alone, relay SI at this station will pick up. The pick-up circuit is effective after relay SA¹ picks up and before relay SAP¹ picks up and extends from (+), back contact 164 of relay SAP¹, front contact 204 of relay SA¹, jumper connection XY and upper winding of relay SI, to (-). Of course, only the SI relay at the station with code (short, short, short) will be up after station registration and its corresponding ST relay at the office will be operated. The circuit will then function to transmit indications from this station (even though they are not new ones) to the control office and they will be as correctly recorded as if a series of new indications were transmitted.

Recheck.—A recheck feature has been provided in this system for the purpose of enabling the operator, in the control office, to put the apparatus through an additional cycle of operations, after indications have been transmitted. There may be some doubt in the operator's mind as to a certain indication being properly displayed. In this event it is only necessary for him to operate a starting button, which will pick up a CD relay and cause the system to go through a cycle of operations. The SO relay, corresponding to the station selected by the starting button, will be picked up at the station in question and at the end of the cycle, before relay SO is dropped, a circuit is closed for operating indication recheck relay IR, extending from (+), back contact 109 of relay SA¹, front contact 195 of relay SAP¹, front contact 196 of relay SO, back contact 197 of relay SI, front contact 198 of relay CH and winding of relay IR, to (-). This circuit is effective at the end of the cycle when relay SA¹ is released and before the release of relays SAP¹ and SO. The operation of relay IR establishes a stick circuit for itself including its front contact 199. Relay IR closes a circuit, at its front contact 201, for energizing thermal relay IRP. Relay IR likewise removes (-), at its back contact 202, from the lower winding of the CH relay, but this latter relay does not release at this time, due to a branch circuit to (-), including contact 203 of the thermal relay. After the necessary time interval required for heating this relay, its contact 203 is broken and relay CH is de-energized. This is effective to close back contact 158, which will put the system through an additional cycle of operations in the manner above described for registering this station in the control office and displaying the required indications.

It will be noted that this same circuit is effective to pick up and stick relay IR on each cycle used for the transmission of controls. On such cycles, however, some relay, such as WP, will be shifted, resulting in the dropping of relay CH, which opens, at its back contact 198, the circuit of relay IR. New indications are transmitted, due to the shifting of a relay such as WP and, shortly after the release of relay CH, relay IR is dropped.

The recheck feature, above described, enables

the operator to initiate a cycle of operations for transmitting indications from a desired station, without transmitting new controls to such a station.

5 *Operation of modification.*—A modification of the station circuits is shown in Fig. 3, which is an arrangement for selecting groups of indications at the same station, without the necessity of providing groups of complete relay equipments. One complete set of relays is provided at the station for controlling most of the circuit operations. The SI relay functions to select the station and it, as well as the stepping relays and other relays shown in Fig. 2, are common to all groups at the same station. It will be understood that group No. 1, indicated in Fig. 3, has a complement of relays as shown in Fig. 2, with the added LC¹ and LCS relays. Group No. 2 and other groups at this same station have only their LC² and CH² and indication relays such as A².

The wires leading off to the right of the drawings are common to the station and connect to relays, such as LC², A² of additional groups, at points corresponding to those indicated associated with group No. 2. Code jumpers 264, 265 and 266 are variably connected at group No. 1 to properly code the time intervals between impulses during transmission of indications, for marking this group for selection. Code jumpers 261, 262 and 263 are variably connected to control the station selecting relay SI. Corresponding code jumpers 274, 275 and 276 at group No. 2 are likewise variably connected to properly code the impulse periods for marking group No. 2 for selection. Likewise, code jumpers 271, 272 and 273 are variably connected to control the station selecting relay SI.

It is believed that the operation of this modification will be best understood by describing briefly the operation when indications are to be transmitted from group No. 1 and from group No. 2. It will be assumed that group No. 1 has an inbound code combination (long, long, short), as indicated by code jumpers 266 and 265 being connected to (+). They preselect the first and second indication code registration periods, respectively. Jumper 264 is omitted so that a short indication code registration period is preselected for the third period. This code combination is likewise indicated by code jumpers 263 and 262 being connected to indication bus 174 for sticking the SI relay during the first and second indication code registration periods, respectively.

55 Group No. 2 is assigned an inbound code (long, long, long). This is indicated by code jumpers 276, 275 and 274 being connected to (+). It will be understood that these code jumpers preselect the time intervals between impulses for the first, second and third indication code registration periods and since they all are connected to (+) potential, all these periods will be long. Code jumpers 273, 272 and 271 are connected to indication bus 174 so that the SI relay will be stuck up during the first three indication code registration periods.

It will thus be seen that the code jumper arrangement departs from the scheme disclosed in connection with Fig. 2, in that these jumpers are not directly selected by the stepping relays but the stepping relays select common wires leading to contacts of all LC relays of a station and the particular LC relay which is picked up extends these common wires to the code jumper connections. In this way a station is selected by making

the SI relay responsive to a number of code combinations and the indication devices such as A¹ and A² are selected after the selection of the station is completed, by means of the particular LC relay which is energized.

CH¹ and CH² are the change relays normally energized and released when a change in indication occurs which requires transmission to the control office. LC¹ and LC² are the interlocking control relays and are for the purpose of permitting only one group at a station to be selected at one time. The operation of these LC relays is by means of a series circuit through contacts of corresponding CH relays, with a cooperating LCS relay which operates and opens the pick-up circuit of the LC relays as long as one of the latter is stuck up.

Assuming that group No. 1 has new indications to be transmitted and that the CH¹ relay is released, in a manner previously explained in connection with Fig. 2, then at the start of the cycle, a circuit is closed for picking up relay LC¹, extending from (+), back contact 251 of relay SA¹, back contact 252 of relay SAP¹, back contact 253 of relay LCS, back contact 254 of relay CH¹, and upper winding of relay LC¹, to (−). Relay LC¹ is stuck up over a circuit extending from (+), back contact 257 of relay 4V¹, in multiple with a circuit to (+) at back contact 255 of relay SI, winding of relay LCS, front contact 256 of relay LC¹ and lower winding of this relay to (−).

Relay LCS operates and opens the pick-up circuit of all LC relays, so that another LC relay can not be energized until the end of this cycle. This stick circuit is effective until relay 4V¹ is picked up to disconnect (+), at its back contact 257 and until relay SI is picked up to disconnect (+), at its back contact 255. The purpose of the stick circuit through contact 255 is to maintain a LC relay stuck up even after relay 4V¹ is operated at the end of a cycle, in the event that the cycle is used for transmitting controls. This holds over an operated LC relay until the start of another cycle, if it is picked up during a control cycle. The operation of relay LC¹ closes a circuit, at its front contact 258, which is effective to pick up the CH¹ relay which was released to initiate this cycle, the circuit extending through contacts 194 and 195 of relays 4V¹ and 3V¹, which circuit was previously described.

Relay LC¹ extends the connection from (+), through code jumper 266, by way of its front contact 259, to the back contact 168 of relay 1V¹ and thence by way of the remainder of the previously described circuit to conductor 205, which is effective to pick up relay PL¹ for preselecting a long code interval on the first step. Likewise, front contact 267 of relay LC¹ connects (+), through code jumper 265 over this same circuit for preselecting a long time interval for the second step. Contact 268 connects to jumper terminal 264, but since there is no jumper at this point, a short time interval is preselected for the third step.

Front contact 269 of relay LC¹ extends the stick circuit of relay SI, connected to indication bus 174, by way of code jumper 263 and front contact 178 of relay 1V¹ to conductor 183, which is connected to (+), at front contact 109 of relay SA¹. This circuit is effective to stick the SI relay at the first step. Front contact 271 of relay LC¹ connects jumper 262 to the above described circuit for sticking the SI relay on the second step. Front contact 278 connects jumper 261 to indication bus 175 for sticking the SI

relay, over the above described circuit, at the third step.

Group No. 2, with an inbound code combination (long, long, long), has its preselecting jumpers 276, 275 and 274 all connected to (+), so that they are effective to respectively preselect long time intervals for the first three code periods. These jumpers are connected to the common conductors leading to contacts of the stepping relays, by means of front contacts 281, 282 and 283 of relay LC². Code jumpers 273, 272 and 271 are all connected to indication bus 174, so that the SI relay will be held by the three long time intervals. These jumpers are connected to the common wires, by way of front contacts 284, 285 and 286 of the LC² relay.

After the particular group of the station is selected, indications are transmitted by means of the long and short time intervals, in a manner previously described in connection with the operation of Fig. 2. Front contact 188 of relay 3V¹ connects conductor 205 leading to relay PL¹, by way of front contact 279 of relay LC¹, to register indications due to the energized or deenergized conditions of relays such as A¹. If group No. 2 is selected, relay LC² is picked up and the above mentioned indication circuit is extended by way of front contact 287 of relay LC², to contacts of indication relays, such as A² associated with group No. 2. It will be understood that relays LC¹ and LC² are supplied with additional contacts similar to 279 and 287 for connecting other indicating devices, similar to relays A¹ and A², during additional steps to conductor 205, for sending additional indications to the control office.

It will thus be seen that two or more code combinations are used for selecting the same SI relay to select a desired station. After the station is selected only one LC relay at the selected station will be picked up, therefore, indications from the selected group at this station will be transmitted. This provides selection of stations by means of the SI relay, selection of groups by means of the LC relay and transmission of indications from the selected group, through the contacts of the selected LC relay.

It will be understood that when an arrangement of this kind is used there will be a relay ST in the control office for each group relay LC at the station, rather than one ST relay for each SI relay, as disclosed in connection with Figs. 1 and 2. It will also be understood that a plurality of stations may be provided with a plurality of groups at each location, operating in the manner explained in connection with Fig. 3 and that duplex operation will be effected, as well as superiority of code, in a manner described in connection with Figs. 1 and 2.

The above rather specific description of the invention is given solely by way of example and is not intended in any manner whatsoever to be in a limiting sense. Obviously, the invention can assume various different physical forms and is susceptible of numerous modifications and all such forms and modifications as come within the scope of the appended claims, are intended to be included within the scope of the invention.

Having described my invention, I now claim:

1. In a centralized traffic controlling system, a control office, a plurality of field stations, a line circuit extending from said control office to said field stations, step-by-step means at said control office and at said field stations responsive to impulses applied to said line circuit, means

for applying a plurality of variably time spaced impulses of distinctive character to said line circuit for operating said step-by-step means at said control office and at said stations in synchronism, means responsive to the character of said impulses on the successive steps of said step-by-step means for selecting one of said stations, and means responsive to the variations in time between said impulses for the successive steps of said step-by-step means for registering any one of said field stations. 5

2. In a centralized traffic controlling system, a control office, a plurality of field stations, a line circuit extending from said control office to said field stations, step-by-step means at said control office and at said field stations responsive to impulses applied to said line circuit, means for applying a plurality of variably time spaced impulses of distinctive character to said line circuit during an operating cycle for operating said step-by-step means at said control office and at said stations in synchronism, means responsive to the character of said impulses on successive steps for selecting a first one of said stations to receive controls from said control office, means responsive to the variations in time between said impulses for the successive steps for selecting a second one of said stations to transmit indications to said control office, and means for continuing the operation of said step-by-step means throughout said cycle at only said first and said second stations. 15

3. In a centralized traffic controlling system, a control office, a plurality of field stations, a line circuit extending from said control office to said field stations, step-by-step means at said control office and at said field stations responsive to impulses applied to said line circuit, signaling devices at said control office and at said field stations, means for applying a plurality of variably time spaced impulses of distinctive character to said line circuit for operating said step-by-step means at said control office and at said stations in synchronism through an operating cycle, means responsive to the character of said impulses for selecting one of said stations and for operating said signaling devices at the selected station during the steps of said operating cycle, and means responsive to the variations in time between said impulses for the steps of said cycle for identifying in the control office another of said stations and for operating said signaling devices in said control office during the steps of said operating cycle. 30

4. In a centralized traffic controlling system, a control office, a plurality of field stations, a line circuit extending from said control office to said field stations, step-by-step means at said control office and at said field stations responsive to impulses applied to said line circuit, signaling devices at said field stations, indicating devices at said control office, means for applying a plurality of variably time spaced impulses of distinctive character to said line circuit for operating said step-by-step means at said control office and at said stations in synchronism through an operating cycle, means responsive to the distinctive character of said impulses for selecting one of said stations and for operating its associated signalling devices thereat on the respective steps during said operating cycle, and means responsive to the variations in time between said impulses for registering said one of said stations and for operating its associated indicating de- 45

70 75 95

vices in said control office on the respective steps during said operating cycle.

5. In a centralized traffic controlling system, a control office, a plurality of field stations, a line circuit extending from said control office to said field stations, step-by-step means at said control office and at said field stations operated in synchronism by impulses applied to said line circuit, impulsive means at said control office for applying a series of impulses to said line circuit and for variably spacing the time intervals between said impulses to form a code combination, means controlled by said code combination through the medium of said step-by-step means for selecting one of said stations, means at said station for preselecting said code combination and causing such preselected code combination to be formed by said impulsive means, and means controlled by said code combination for registering 20 said selected station in said control office.

6. In a centralized traffic controlling system, a control office, a field station, a line circuit extending from said control office to said field station, impulsive means at said control office for applying a series of time spaced impulses on said line circuit, step-by-step means at said control office and at said field station operated in synchronism in response to said series of impulses applied to said line circuit, means at said station for opening and closing said line circuit on certain steps of said step-by-step means to form a code, means at said control office responsive to said opening and closing of said line circuit at said field station for causing said impulsive means 35 to provide long and short time intervals respectively between said impulses to form said code combination, and means at said station distinctively responsive to said code combination.

7. In a centralized traffic controlling system, a control office, a plurality of field stations, a line circuit extending from said control office to said field stations, step-by-step mechanism at said control office and at said field stations responsive to impulses applied to said line circuit, impulsive means at said control office for applying a series of impulses to said line circuit during an operating cycle for advancing said mechanism in synchronism, code means at said control office for causing said impulsive means to provide long and short time intervals between said impulses to form different code combinations, means controlled at a first one of said stations for determining that a code combination for selecting said first station be caused by said code means during 50 said operating cycle of said step-by-step mechanism, and means controlled at a second one of said stations for changing the control of said first station over said code means so that a code combination is caused which will select said second station in preference to said first station during said operating cycle.

8. In a centralized traffic controlling system, a control office, a first field station, a second field station, a line circuit connecting the control office with the field stations, step-by-step mechanism at the control office and at the stations responsive to impulses on said line circuit, means at the control office for applying a series of impulses to the line circuit to comprise an operating 65 cycle for advancing said mechanism step by step in synchronism, station selecting means at the stations initially conditioned for operation at the start of said cycle, means controlled by said first field station for opening the line circuit during certain steps of said mechanisms, and means in the

control office responsive to the opening of the line circuit by said first station for continuing the operation of the station selecting means at said first station and disabling the operation of the station selecting means at said second station. 5

9. In a centralized traffic controlling system, a control office, a first field station, a second field station, a line circuit connecting said control office with said field stations, step-by-step mechanism at the control office and at the stations responsive to impulses on said line circuit, means at the control office for applying a series of time spaced impulses to the line circuit during an operating cycle for advancing said mechanisms step by step in synchronism, station selecting means 10 at the stations initially operated at the start of said cycle, means controlled by said first field station for momentarily opening the line circuit during certain predetermined steps of said mechanisms, means in the control office responsive to 15 said momentary openings for extending the time interval between associated impulses for the corresponding steps, and means responsive to said extension of certain time intervals for continuing the operation of the station selecting means 20 at said first field station and disabling the operation of the station selecting means at said second station.

10. In a centralized traffic controlling system, a control office, a plurality of field stations, a line circuit extending from the control office to the field stations, means at the control office for applying a series of impulses to the line circuit to comprise an operating cycle, timing means at the control office for providing long and short time 30 intervals between impulses to form code combinations, a starting relay in the control office manually controllable in the control office and automatically controllable over said line circuit from said field stations for initiating said operating cycle, means at said stations for conditioning said line circuit to determine the short and long duration of said time intervals as applied by said timing means to form a particular code, means at the control office for registering said 35 particular code, and means at said field station controlled by said code combination for selecting a particular one of said field stations. 40

11. In a centralized traffic controlling system, a control office, a field station, a normally closed line circuit extending from the control office to the field station, means at the control office for opening and closing the line circuit to form a series of time spaced impulses, step-by-step mechanism at the control office and at the field station operated in synchronism by said impulses, code selecting means at the field station rendered successively effective by said stepping mechanism to predetermine the normal or abnormal time space between successive impulses, 50 and means at the control office responsive to said 55 code selecting means for changing a normal to an abnormal time space.

12. In a centralized traffic controlling system for railroads, a control office, a plurality of field stations, a communicating circuit extending from the control office through the several field stations, means in the control office for applying impulses of current to said communicating circuit at uniformly time-spaced intervals, stepping 65 relays at the control office and at each station operated sequentially by said impulses, means at each station effective to selectively extend the time-space between said communicating circuit 70 impulses, and means at the control office respon- 75

sive only to an extended time-space between impulses.

13. In a centralized traffic controlling system for railroads, a control office, a plurality of field stations, a communicating circuit extending from said control office through each of the several stations, means at the control office for applying normally time-separated impulses of current to said communicating circuit, stepping relays at the control office and at each station operated sequentially by said impulses, selective means at each station operable successively by associated stepping relays to either extend or leave normal the time separation between said impulses in accordance with a distinctive code call for that station, means at each station distinctively responsive to the length of time separation between successive impulses for rendering said selective means at that station ineffective whenever the length of time separation between any two successive impulses fails to correspond to the code call for that station, and station registering means in the control office governed successively by the length of the time separation between impulses.

14. In a centralized traffic controlling system for railroads, a control office, a field station, a plurality of traffic controlling devices at said field station, a line circuit connecting said control office and said field station, means in said control office for impressing a series of time spaced distinctive impulses on said line circuit, and means at said field station for distinctively determining the duration of said time spaces, whereby controls and indications are simultaneously transmitted to and from said plurality of traffic controlling devices.

15. In a centralized traffic controlling system for railroads, a control office, a plurality of field stations, a line circuit connecting said control office and said field stations, means at said control office for impressing a plurality of different series of distinctive impulses on said line circuit, station selecting means at each field station responsive only to that particular series of impulses characteristic of that station, transmitting means at each of said stations effective to vary the timing of the impulses of any of said series when that station is rendered effective to transmit, means allowing the transmitting means to be rendered effective at only one station for each series irrespective of the number of stations then ready to transmit, and station registering means at the control office responsive to the variations in the timing of the impulses of any series to register that station of which the timing for that series is characteristic, whereby any station may be selectively controlled during the same cycle of operation that the same or some other station may be selectively registered.

16. In a centralized traffic controlling system for railroads, a control office, a field station, a line circuit connecting said control office and said field station, means in said control office for impressing a series of uniformly time spaced impulses on said line circuit, means at said station capable to selectively extend the time spaces between said impulses, and means in said control office distinctively controlled dependent upon whether the time spaces are of uniform or of extended durations.

17. In a centralized traffic controlling system for railroads, a control office, a plurality of field stations, a line circuit connecting said control

office and said field stations, means in said control office for impressing a series of uniformly time spaced impulses on said line circuit, step-by-step means at said control office and at each field station responsive to take one step for each of said time spaces irrespective of their duration, means at each field station selectively effective to extend the time spaces for each step to thereby form a code combination, and means at each field station and at said control office responsive to the code combination formed by said time spaces.

18. In a centralized traffic controlling system for railroads, a control office, a plurality of field stations, a line circuit connecting said control office and said field stations, means at said control office for impressing any one of a plurality of different series of impulses on said line circuit, means at each field station responsive to certain of said different series of impulses, whereby controls may be transmitted to any particular station, means at each field station for conditioning said line circuit with any one of a plurality of distinctive conditions for each successive impulse only if the distinctive conditions for the preceding impulses have agreed with the code call of that station, with said distinctive conditions having relative degrees of superiority, whereby a more superior condition imposed by a station on said line circuit cancels all inferior conditions imposed on said line circuit by any of the remaining stations, and means at said control office and at each of said field stations for indicating the surviving condition imposed on said line circuit by said field station, whereby indications may be transmitted to said control office from only one field station during any one series of impulses irrespective of the number of field stations having indications standing ready for transmission.

19. In a centralized traffic controlling system for railroads, a control office, a plurality of field stations, a line circuit connecting said control office and said field stations, means at said control office for impressing a plurality of series of distinctive impulses on said line circuit, step-by-step means at said control office and at said field station responsive to take one step for each of said impulses of any one series, means at each field station responsive to the distinctive character of the impulses of a series, pulsing means at each field station for at times controlling the duration of the time spaces between successive impulses of any series in accordance with a distinctive code call belonging to that station, said pulsing means at any such sending stations being automatically rendered ineffective on any step if the time space duration for that step does not match the code call for that station, and station registering means in the control office distinctively governed by the successive distinctive time spaces of each series.

20. In a centralized traffic controlling system for railroads, a line circuit extending from a control office to a distant field station, means at the control office for applying positive and/or negative normally timed spaced impulses to said line circuit, manually operable means for determining the positive or negative character of each impulse, electro-responsive means at the field station distinctively controlled in accordance with the positive and/or negative characters of said impulses, means at the field station acting automatically to selectively determine whether each time space between any two of said impulses shall be normal or prolonged in accordance with

the condition of its particular one of a plurality of devices, and electro-responsive means at the control office distinctively controlled in accordance with the normal and/or prolonged time spaces between said impulses.

21. In a centralized traffic controlling system for railroads, a line circuit extending from a control office to a distant field station, means at the control office for applying a series of impulses of distinctive characters, means at the control office for distinctively determining the distinctive characters of the impulses of any series, means at the field station for selecting normal and/or extended time separation between the impulses of any series, means at the field station distinctively controlled in accordance with the characters of the impulses of any series, and means at the control office and at the field station simultaneously and distinctively controlled in accordance with said normal and/or extended time separation between the impulses of any series.

22. In a remote control system, two stations connected by a single line circuit, a series of movable devices at each station, means for transmitting over said line circuit a series of time-spaced impulses of current, comprising means at one station for selectively controlling the time intervals between consecutive impulses of said series, means at the other station for selectively controlling the relative polarity of each impulse of said series; means effective to control the devices at said one station each in accordance with the relative polarity of a particular impulse of said series, and means effective to control the devices at said other station each in accordance with the relative length of a particular time interval between consecutive impulses of said series.

23. In a remote control system, a receiver comprising a two-position relay adapted to be actuated repeatedly from one position to the other by consecutive elements of a series of timed impulses of current, a slow release relay adapted to become released if said relay remains in said one position for more than a predetermined time interval, a series of polarized indication relays, one for each element, and means rendered effective each time said relay is actuated to said other position for energizing a selected one of said indication relays to one position provided said slow release relay is then energized and to another position provided said slow release relay is then deenergized.

24. In a remote control system, two stations connected by a single line circuit, stepping apparatus at each station, means for transmitting over said line circuit a series of time-spaced impulses of current of selected relative polarity, said impulses being effective to operate the stepping apparatus at the two stations in unison, irrespective of the time spacing or polarity of the impulses, means controlled by said stepping apparatus and effective at one station to selectively control the relative polarity and at the other station to selectively control the time-spacing of the impulses, means at the one station selectively responsive to the time-spacing of the impulses, and means at the other station selectively responsive to the relative polarity of the impulses.

25. A normally-at-rest remote control system comprising two stations connected by a single line circuit, stepping apparatus at each station adapted when set into operation to operate

through a cycle, means for transmitting over said line circuit a series of time spaced impulses of current to actuate the stepping apparatus at the two stations in unison, means controlled by said stepping apparatus and effective at one station to selectively control the relative polarity of the impulses, and at the other station to selectively control the time-spacing of the impulses, means controlled by the stepping apparatus at the one station selectively responsive to the relative polarity of the impulses of said series, means controlled by the stepping apparatus at the other station selectively responsive to the timing of the impulses, and means at each station for setting said stepping apparatus into operation.

26. In a remote control system, an office and a plurality of stations connected by a line wire, stepping apparatus at the office and at said stations, means for transmitting over said line wire a series of variably time-spaced impulses of current of selected relative polarities to actuate the stepping apparatus at the office and stations in unison, irrespective of the polarity or time-spacing of said impulses; a plurality of selector relays, including one at each station and a corresponding relay for each station at the office, means effective to control each station selector relay in accordance with the relative polarity of a portion of said series of impulses, means effective to control the corresponding office relay in accordance with the time spacing of certain of said impulses, manually operable means at the office for controlling the relative polarity of said impulses, and means at each station for controlling the time spacing of the impulses.

27. A centralized traffic control system for simultaneously transmitting controls and indications between a control office and a field station comprising, a single line circuit connecting the control office and the field station, means in the control office responsive to the intermittent de-energization of said line circuit for energizing said line circuit successively with current of a polarity varied in accordance with the controls to be transmitted, means at the field station responsive to the intermittent de-energization of said line circuit for controlling its continuity to vary the time spacing between successive energizations of the line circuit, means at the control office responsive to the variations in the time spacing between successive energizations of the line circuit, and means at the field station responsive to the polarity of the successive energizations of said line circuit.

28. A centralized traffic control system for simultaneously transmitting controls and indications between a control office and a field station comprising, a single line circuit connecting the control office and the field station, a step-by-step means in the control and at the field station operated synchronously in response to successive deenergizations of said line circuit, means in the control office controlled by said step-by-step means at the control office for energizing said line circuit with direct current impulses of polarities varied in accordance with the controls to be transmitted, means at the field station governed by said step-by-step means at the field station for opening said line circuit to prolong the time spacing between succeeding impulses in accordance with the indications to be transmitted, control means at the field station governed by said step-by-step means at the field station and distinctively controlled in accordance with the polarity of successive energiza-

- tions of said line circuit, and indicating means in the control office governed by said step-by-step means at the control office and distinctively conditioned for each energization of said line circuit in accordance with the length of the next preceding time space between energizations.
29. A centralized traffic control system for transmitting indications from a field station to a control office comprising, a normally energized single stepping and indication line circuit connecting the field station with the control office, a plurality of changeable devices at the field station to have their conditions indicated in the control office, a normally energized stick relay, a stick circuit for said stick relay controlled by all of said devices and momentarily opened upon a change in the condition of any device, means controlled by said stick relay for opening said line circuit to initiate operation of the system, and means including a line relay in said line circuit and stepping relays operated by said line relay for varying the time duration of successive deenergizations of said line circuit in accordance with the condition of said devices.
30. In a remote control system, an office and a plurality of stations connected by a line circuit, a code transmitter at the office and at each station for controlling said line circuit, a stick relay at each station, means effective when each stick relay is energized to operate the associated transmitter to determine the character of the time-spaced elements of a multiple element code impressed upon the line circuit, each such code being different from the others in the length of at least one element, code receiving means at the office responsive to the codes delivered to the line circuit, independently operable means for picking up said stick relays, means for releasing each energized stick relay at the end of a complete code, and means effective in the event a plurality of said transmitters are set into operation at the same time to discontinue the operation of all but one comprising means for releasing each station stick relay on any step of a code in response to the delivery to said line circuit of a code element which is not in accordance with the code then being transmitted by the code transmitter which such stick relay controls.
31. In a centralized traffic control system for railroads, a control office and a plurality of field stations connected by a single line circuit, a line relay at each station included in said line circuit, a stick relay at each station, transmitting means at each station operable only if the corresponding stick relay is energized for controlling the continuity of said line circuit on successive steps to determine the time character of the elements of a multiple element code, said code for each station being different from the codes for all of the other stations in the duration of at least one of such elements, means at each station for temporarily closing an energizing circuit for the corresponding stick relay, and means including a stick circuit for each stick relay for maintaining that relay energized unless the duration of opening of said line circuit at any one of the successive steps as manifested by the operation of the line relay at such station is longer than that required by the code belonging to that station.
32. In a system for transmitting indication codes from a plurality of stations one at a time to a control office, a single line circuit connecting the control office and the several stations, a line relay at each station included in said line circuit, a stick relay at each station, a transmitter relay at each station for controlling the continuity of said line circuit, means at each station including said transmitter relay and a time responsive device and effective only if said stick relay at that station is energized for determining the short or long open condition of said line circuit on successive steps to give distinctive character to each of the elements of a multiple element code, said code for each station being different from the codes for all other stations in the duration of at least one of said code elements, a plurality of changeable devices at each station to be indicated in the control office, means at each station responsive to a change in the condition of any one of said changeable devices for initially energizing said stick relay at that station to initiate the transmission of a code, a holding circuit for said stick relay at each station including contacts responsive to the operation of said transmitter relay and said line relay for maintaining said stick relay energized only so long as the continuity of said line circuit on each step corresponds with the code belonging to that station, and station registration means in the control office responsive to the condition of said line circuit on the successive steps as determined by the transmitting relay of the station or stations then effective, whereby in the event that a change occurs at a plurality of field stations tending to cause transmission of a code from such stations at the same time, the stick relays of all but one of such stations are de-energized on the successive steps to leave only one transmitting relay effective, and the particular code for that surviving station is the one registered in the control office.
33. In a system for transmitting indication codes from a plurality of field stations one at a time to a control office, a single line circuit connecting the control office and the several field stations, a line relay at each station in said line circuit, a station selecting relay at each station, transmitting means at each station including stepping relays and effective only if said station selecting relay of that station is then energized for governing the continuity of said line circuit on successive steps to cause the line circuit to be open for a short or a long time interval in conformity with a distinctive code allotted to such station, such distinctive code for each station differing from the codes for all other stations in the duration of at least one of said time intervals, changeable devices at each station having different conditions to be indicated in the control office, means responsive to a change in the condition of said devices at a station for energizing said station selecting relay at that station, means at each station for automatically deenergizing and maintaining de-energized said station selecting relay at such station on any one of the successive steps to discontinue operation of the corresponding transmitting means whenever the line relay at such station is maintained de-energized by the transmitting means of some other station for a long interval on a step for which the code belonging to such station requires a short interval, and station registration relays in the control office responsive to the long or the short time interval on each of the successive steps as determined by the transmitting means of the station or stations still in operation on such step.
34. A system for transmitting indication codes from a plurality of field stations one at a time to a control office comprising, a single line circuit

- connecting the control office and the several field stations, transmitting means at each station including stepping relays for governing the continuity of said line circuit at certain times to provide a long or a short time interval on each of the successive steps in accordance with a distinctive code allotted to such station, such distinctive code for each station being different from the codes for all other stations in the duration of at least one of said time intervals, means for initiating the operation of said transmitting means at each station when new indications are to be sent to the control office from that station, means at each station for automatically discontinuing the operation of the transmitting means at that station on any one of the successive steps if the condition of said line circuit on such step as determined by the transmitting means of some other station does not match the distinctive code for such station, and station registration means in the control office responsive to the duration of such time intervals for each of the successive steps as determined by such transmitting means at a station or stations as are still in operation at the time of such step.
35. In a remote control system; a control office; a plurality of field stations; a single communicating circuit extending from the control office through the several field stations; means in the control office for applying to the communicating circuit any one of a plurality of different combinations of impulses distinctive by their polarity, each of said different combinations being a characteristic code call for one of said stations and the controls for that station; manually controllable means for determining the particular one of said combinations to be applied to said communicating circuit at any one time; stepping apparatus at the control office and at each of said field stations operated in unison in response to the impulses on said communicating circuit irrespective of the polarity or time spacing of such impulses; station selecting and control means at each of the field stations controlled by its stepping apparatus and selectively responsive to the relative polarity of the impulses of those of said combinations having the characteristic code call for its station; means at each station controlled by its stepping apparatus and operable to selectively determine the duration of the time space between successive impulses to form combinations to conform with the distinctive code call for that station and the indication to be transmitted to the control office; and indication means at the control office controlled by its stepping apparatus and controlled in accordance with the combinations of time spacing of said impulses to register the code call and indications of the station transmitting.
60. In a centralized traffic controlling system for railroads, a control office, a plurality of field stations, a communicating circuit extending from said control office through each of said stations, impulsing means at the control office for applying normally time-spaced impulses to said communicating circuit by opening and closing such circuit, stepping relays at the control office and at each field station operated sequentially by said impulses, transmitting means at each station controlled by stepping relays at that station selectively operable to open the communicating circuit at a time between normally spaced impulses and arranged to close said communicating circuit after such time-space between said impulses has been abnormally extended, and means at the control

office responsive to an abnormally extended time-space between impulses for causing said impulsing means to close said communicating circuit at the end of an abnormally extended time-space only after the communicating circuit has been closed by the transmitting means at all of said field stations. 5

37. In a centralized traffic controlling system for railroads, a control office, a plurality of field stations, a communicating circuit extending from the control office through each of said stations, means at the control office for applying a series of normally time-spaced impulses of current to said communicating circuit, stepping relays at the control office and at each field station operated sequentially by said series impulses, registering means at said control office associated with each field station, transmitting means at each field station rendered effective by said stepping relays at that station to extend or leave normal the time-spaces between the successive impulses of the series in accordance with a code characteristic of such station, and means at the control office distinctively responsive to the normal or extended time-spaces of said series and rendered effective by said stepping relays at the control office to control said registering means for that station corresponding to the code formed by such time-spaces. 20

38. In a centralized traffic controlling system, a control office, a plurality of field stations, a line circuit extending from said control office to said field stations, step-by-step mechanisms at said control office and at said field stations responsive to impulses applied to said line circuit to operate through a cycle of operation, means at said control office for applying a series of distinctive impulses to said line circuit during an operating cycle for advancing said mechanisms in synchronism and for transmitting controls to any desired field station, receiving means at each field station controlled by the step-by-step mechanism and responsive to the distinctive impulses of a series for selecting that station and receiving its controls, transmitting means at each field station for at times distinctively varying the condition of said line circuit on the successive steps of said step-by-step mechanisms in accordance with a code to identify its station and in accordance with indications to be transmitted, receiving means at said control office for automatically testing the condition of said line circuit on the successive steps of said step-by-step mechanisms so as to be distinctively responsive to the variation in conditions as effected by the transmitting means at the field stations, and storing means controlled by said receiving means at the control office on the successive steps of said mechanisms for translating the code received into a station identification for registering such station and then storing the indications transmitted from such station. 40

39. In a centralized traffic controlling system, a control office and a plurality of field stations, a single line circuit connecting said control office with said field stations, impulsing means at said control office for applying a series of normally time spaced impulses to said line circuit, a step-by-step mechanism at said control office and at each of said field stations responsive to said series of impulses on said line circuit to operate through a cycle of operation, transmitting means at each of said stations operable when rendered effective to pro- 70 75

long the time spaces of a series of impulses in accordance with a code, a plurality of indication devices at each of said field stations, certain of said field stations having a large number of indication devices which are divided into a plurality of indication groups, a group of code jumpers for each of said field stations and in the case of those stations having a plurality of indication groups there being a group of code jumpers 5 for each of such indication groups, means effective upon a change in the condition of an indication device for initiating said transmitting means at its station and causing it to transmit a code in accordance with the code jumpers for 10 its station or indication group as the case may be so long as said transmitting means is rendered effective, and a station selecting relay at each of said stations initially picked up at the beginning of a cycle of operation and maintained 15 picked up throughout the cycle of operation only if the duration of the time spaces between the impulses of that cycle corresponds to the code then being transmitted by said transmit- 20

ting means at its station, said station selecting relay rendering said transmitting means at its station effective only while it is picked up.

40. In a centralized traffic controlling system for railroads, a control office, a field station, 5 traffic controlling devices at said field station, a single line circuit connecting said control office and said field station and energized only by a direct current source located at said control office, and means for simultaneously transmitting controls to said devices and indications from said devices between said control office and said field station over said single line circuit, said means including means at said control office for impressing a control code comprising a 10 series of code elements each including a distinctive current impulse from said direct current source on said line circuit and a time space and means at said field station for distinctively and 15 individually modifying some of the individual 20 code elements of said series of code elements.

THOMAS J. JUDGE.
